[57] ABSTRACT

A substantially continuous ribbon of a thermoplastic material supporting a plurality of depending and equally spaced-apart articles or bodies and moving in a generally linear direction through a first path of travel at a relatively high rate of speed is periodically fractured at equally spaced-apart points along the length thereof to successively provide a series or succession of ribbon lengths each supporting an equal number of the pendent articles, and successive ones of the ribbon lengths are handled and delivered to ribbon-length receiving and transfer means without contacting any of the pendent articles or bodies of such ribbon lengths. The thermoplastic ribbon may, for example, be a ribbon of a glassy material from which the pendent articles or bodies are integrally formed by glass forming apparatus while the ribbon moves through said first path of travel, and the apparatus for fracturing, handling and delivering the ribbon lengths includes a plurality of ribbon-length pickup devices which are located in a second path of travel generally collinear with said first path of travel and each of which are alternately moved and actuated by cam means to follow and pickup successive ones of the moving ribbon lengths, move each such length into clearance of the next following ribbon length, and deliver each picked-up length to said ribbon-length receiving and transfer means.

ARTICLE HANDLING APPARATUS AND METHOD

This is a division of our copending application Ser. No. 82,466 filed Oct. 20, 1970, now U.S. Pat. No. 3,690,527.

BACKGROUND OF THE INVENTION

In the manufacturing of containers, for packaging foods and beverages for human consumption for example, it is desirable that such containers have a relatively high strength or resistance to breakage, and a ready suitability for cleansing or sterilizing as well as an inherent cleanliness. Containers made of thermo-plastic materials such as glass ideally provide the latter characteristics. The container manufacturing industry is, today, a highly competitive industry and, therefore, for competitive considerations, as well as other obvious economic reasons, it is expedient to manufacture containers having as light a weight as practicable with consideration to the required strength and breakage resistance characteristics of such containers, and to make such containers at as high a rate of speed as possible. Accordingly, ways are continuously being sought to increase the speed of manufacture of containers of the type discussed as well as other similar containers.

There is shown and described in U.S. Pat. No. 1,790,397, issued Jan. 27, 1931 to William J. Woods and David E. Gray, and assigned to the same assignee as the present application, an apparatus for manufacturing lightweight hollow glass bodies or articles at an extremely high rate of speed. Such an apparatus is capable, for example, of manufacturing bulbs or envelopes for electric lamps at a rate of approximately 7200 per hour. A similar machine for high speed manufacturing or forming of light weight containers, such as the food and beverage containers discussed above, has recently been developed. In the course of such development, the problems of conveying the manufactured or formed containers away from the container manufacturing or forming machine at high rates of speed, and of otherwise handling the containers at rates of speed corresponding to the rates of speed of manufacture or forming thereof, were recognized. It was also recognized that the containers should be conveyed and handled at the required speeds so that the bodies of such containers are, preferably, not contacted and, thereby, possibly scuffed, scratched or scored prior to strengthening of the containers, by annealing thereof for example, or prior to applying abrasion-resistant coatings to the containers. Accordingly, the apparatus and method of the present invention was developed for the handling of said containers in such desired manner.

SUMMARY OF THE INVENTION

In practicing the invention herein disclosed, there is provided and employed in conjunction with a substantially continuous ribbon of thermoplastic material supporting a plurality of equally spaced-apart pendent articles or bodies and moving at a relatively high speed in a selected forward direction through a selected path of travel, a ribbon crack-off or fracturing device for successively breaking said ribbon at equally spaced-apart points along the length of such ribbon while it moves through a second path of travel extending generally collinear with said selected path and past said fracturing device, such breaking of said ribbon providing a succession of adjacent or abutting end-to-end ribbon

lengths each supporting a bank of the same or an equal number of said articles or bodies. In said second path of travel beyond said fracturing device there is provided and employed an apparatus including cam-actuated first and second pickup devices for alternately following and picking up successive ones of said ribbon lengths and, thereby, providing clearance between the trailing edge of the respective picked-up ribbon length and the next succeeding ribbon length; moving each pickup device and, thereby, each respectively picked-up ribbon length in a direction extending laterally to said second path of travel to clear the path for movement therethrough of the next succeeding ribbon length; and thereafter actuating each respective pickup device to deliver each respectively picked-up and handled ribbon length to conveyor means for receiving and conveying each such length away from the location of said pickup devices. Said first and second pickup devices are continuously alternately operated to handle alternate successive ones of said ribbon lengths in the manner outlined and, when one of the devices is moving in said forward direction, the other of such devices is moving in the opposite or reverse direction to return the respective device to a position to handle a succeeding one of said ribbon lengths. When said ribbon moves at a speed such that one pair of said pickup devices is unable to satisfactorily handle succeeding ones of the cracked-off ribbon lengths, an additional pair of the pickup devices and associated apparatus may be provided at each of one or more succeeding and additional locations in said second path of travel to correspondingly handle succeeding ones of said ribbon lengths which are permitted to pass the location of the first and second pickup devices. For example, of two sets of apparatus each including a pair of pickup devices are provided at each of two successive pickup stations or locations in said second path of travel, the pair of pickup devices at the first pickup station or location can be operated to alternately handle only odd-numbered ones of the succession of ribbon lengths while the pair of said devices at the second pickup station or location is operated to alternately handle even-numbered ones of the succession of ribbon lengths.

Additional modifications and characteristic features of the invention will become apparent to those skilled in the art in the light of the part of the specification which follows and as the description proceeds.

BRIEF DESCRIPTION OF THE DRAWINGS

In the drawings:

FIG. 1 is a top plan view of the apparatus embodying the invention;

FIG. 2 is a front elevational view of part of the apparatus of FIG. 1, such view being taken generally along line 2—2 of FIG. 1;

FIGS. 2a, 2b and 2c comprise views of portions of the apparatus of FIG. 2, such views being on an enlarged scale and illustrating details of such apparatus portions;

FIG. 3 is an end elevational view of the apparatus of FIG. 1, such view being taken generally along line 3—3 of FIG. 1;

FIG. 4 is an enlarged detail view of a part of the apparatus comprising the invention, such view being taken generally along line 4—4 of FIG. 2;

FIG. 5 is an enlarged view of a portion of the apparatus shown in FIG. 4, such view being taken generally along line 5—5 of FIG. 4;

FIG. 6 comprises a view taken along line 6—6 of FIG. 5 and further illustrating details of the apparatus;

FIGS. 7, 8 and 9 are views illustrating configurations of parts of the apparatus embodying the invention;

FIG. 10 is a top-plan view on an enlarged scale and showing in greater detail a portion of the apparatus of FIGS. 2 and 4, such view being taken in general along line 10—10 of FIG. 2;

FIGS. 11 through 14 further illustrate details of the apparatus of FIG. 10, such views being taken generally along lines 11—11, 12—12, 13—13 and 14—14, respectively, of FIG. 10;

FIG. 15 is taken generally along line 15—15 of FIG. 1 and is on an enlarged scale to illustrate details of a small part of the apparatus of FIG. 1;

FIGS. 16, 17 and 18 are taken substantially along lines 16—16, 17—17 and 18—18, respectively, of FIG. 15 to further illustrate details of the apparatus embodying the invention;

FIGS. 19 and 20 comprise isometric views further illustrating parts of the apparatus shown in FIGS. 1 and 15;

FIG. 21 is an enlarged view similar to that of FIG. 15 and is taken generally along line 21—21 of FIG. 1;

FIG. 22 comprises a front elevational view of another part of the apparatus used in practicing the invention disclosed;

FIGS. 22a, 22b and 22c are enlarged detailed and fragmental views of portions of the apparatus of FIG. 22, views 22b and 22c being taken substantially along lines 22b—22b and 22c—22c, respectively, of FIG. 22a;

FIG. 22d comprises an enlarged top plan view of a part of the apparatus shown in FIGS. 22 and 22c;

FIGS. 22e and 22f views taken along line 22e—22e and 22f—22f, respectively, of FIG. 22d;

FIG. 23 comprises a sectional view taken generally along line 23—23 of FIG. 22;

FIG. 23a is a view similar to FIG. 23 and taken generally along line 23a—23a of FIG. 22;

FIG. 23b is an end view of part of the apparatus of FIG. 22, such view being taken generally along line 23b—23 of FIG. 22;

FIG. 24 is an enlarged elevational view of part of the apparatus shown in FIG. 3;

FIG. 25 comprises an elevational view taken generally along line 25—25 of FIG. 24;

FIG. 26 is a table detailing the shape of a cam groove embodied in a cam employed in practicing the invention disclosed;

FIGS. 27, 28 and 29 are schematic diagrams illustrating movement of parts of the apparatus of the invention during a cycle of operations thereof;

FIG. 30 comprises a schematic diagram illustrating movement of additional parts of the apparatus during said cycle of operations thereof; and

FIG. 31 is a time chart illustrating examples of relative speeds of parts of the apparatus of the invention during several different operational speeds of the overall apparatus.

Similar reference characters refer to similar parts in each of the figures of the drawings.

PREFERRED EMBODIMENT OF THE INVENTION

Referring to the drawings in detail, there is shown in FIGS. 1, 2 and 3 of the drawings a first handling station at which an apparatus supporting framework 10 comprising cross members 11, 12, 13 and 14 which are supported by upright members or legs 16, 17 and 19 whose bottom ends rest on a floor or suitable platform designated generally as 20 in FIG. 3. Said cross members and upright members may, for example, be welded to each other to form the framework 10. A pair of additional support members 21 and 22 extend between and rest on members 11 and 12, such members being secured to each other as by welding for example.

A cylinder or drum cam 25 including the usual axle 26 is supported on the upper surface of support members 21 and 22 by a pair of pillow blocks 23 and 24 through which axle 26 extends in the usual rotatable relationship therein. Pillow blocks 23 and 24 are secured to the upper surfaces of support members 21 and 22, respectively, as by welding such blocks to such support members. Drum cam 25 includes about the outer periphery thereof a cam groove 27 having circumferential sections or portions 27a and 27b, and a spiral or helical section or portion 27c which joins the circumferential sections or portions of cam groove 27 with each other. Cam 25 and its cam groove 27 will be discussed in more detail hereinafter.

A first gear box 30 is mounted on the top surfaces of cross members 12 and 13 while a second gear box 31 is similarly mounted on the top surfaces of members 11 and 13. Gear box 31 includes an input shaft 32 (FIG. 3) to be further discussed hereinafter, and first and second sprocket wheels 33 and 34 mounted on output shafts of the gear box in a driven relationship with such output shafts, as is well known in the art. Gear box 30 includes a sprocket wheel 35 mounted on an input shaft of the gear box in a driving relationship with such input shaft and a sprocket wheel 36 mounted on an output shaft of the gear box in a driven relationship with such output shaft.

A pair of sprocket wheels 38 and 39 are mounted on the left hand end (viewing FIG. 1 of the drawings) of axle 26 of cam 25 and are keyed to such axle for driven and driving relationships therewith, respectively. An endless drive chain 41 loops about sprocket wheels 34 and 39 in the usual well known manner while another endless chain 42 similarly loops about sprocket wheels 35 and 38. By the arrangement illustrated, proper rotation imparted to drive shaft 32 of gear box 31, as hereinafter further discussed, will impact counterclockwise rotation to sprocket wheels 34 and 39 to in turn drive axle 26 and, thereby, cam 25 and sprocket wheel 38 in corresponding directions. Such counterclockwise rotation of sprocket wheel 38 will impart counterclockwise rotation to sprocket wheel 35 of gear box 30 for a purpose discussed hereinafter. During the above mentioned counterclockwise rotation of sprocket wheel 34, gear box 31 imparts counterclockwise rotation to sprocket wheel 33 while gear box 30, during the counterclockwise rotation of sprocket wheel 35, imparts clockwise rotation to sprocket wheel 36.

There is provided adjacent the front side of cam 25 a sprocket wheel arrangement including driven sprocket wheels 46 and 47 and idler sprocket wheels 48 and 49. An endless chain 50 loops about sprocket wheel 46 and

previously mentioned sprocket wheel 36. Another endless chain 51 loops about sprocket wheels 47, 48 and 49. During the previously mentioned counterclockwise rotation of sprocket wheel 35 of gear box 30, sprocket wheel 36 of such gear box is driven in a direction to impart, through chain 50, rotation to sprocket wheel 46 and corresponding rotation to sprocket wheel 47 which is keyed to the same shaft or axle as sprocket wheel 46. Chain 51 is, thereby, driven so that the lower part of the loop of such chain moves in a direction from right to left when viewing FIG. 2 of the drawings. Chain 51 and its purpose will be discussed further hereinafter in this description.

There is also provided adjacent the back side of cam 25 a sprocket wheel arrangement similar to that just discussed and including driven sprocket wheels 56 and 57 and idler sprocket wheels 58 and 59. An endless chain 60 loops about sprocket wheel 56 and previously mentioned sprocket wheel 33. Another endless chain 61 loops about sprocket wheels 57, 58 and 59. During the previously mentioned counterclockwise rotation of sprocket wheel 34, gear box 31 imparts rotation to sprocket wheel 33 of such gear box to drive sprocket wheels 56 and 57 in corresponding directions since wheel 57 is keyed to the same shaft or axle as sprocket wheel 56 and this latter wheel is driven by chain 60. Chain 61 is driven by sprocket wheel 57 in a direction such that the lower part of the loop of such chain moves in a direction from right to left similarly to chain 51 previously discussed. It is pointed out that some of the details of the sprocket wheel arrangement adjacent the back side of cam 25 are not shown in the drawings for purposes of simplification thereof but the arrangement will be readily apparent to those skilled in the art from a brief glance at FIG. 1 and from the description of the sprocket wheel arrangement adjacent the front of cam 25 and shown in FIG. 2 since both sprocket arrangements are similar.

Referring now to FIGS. 4 through 14 taken in conjunction with FIGS. 1 through 3, there is shown in FIG. 4 a main carriage or sliding support member 65 which is supported on framework 10 for reciprocative sliding movement below cam 25, and between the front and rear of framework 10. The left hand end of member 65 (viewing FIG. 1) is supported for said sliding movement by a shaft 66 extending between and secured to members 11 and 12 of framework 10, and through suitably fitting bushings 67 and 68 carried on the left hand end of member 65. The right hand end of member or carriage 65 is provided with rollers or wheels 69 and 70 rotatably mounted on member 65, and extending into a channel or track 71 in a support member 72 which also extends between members 11 and 12 and is secured thereto.

One end of an actuating arm 73 is pivotally connected to a cross member 74 (FIG. 3) suitably secured to carriage or support 65 adjacent the rear thereof and the other end of actuating arm 73 is pivotally connected to a crank arm 75 secured to the output shaft 76 of an oscillatory gear box 77 which is fastened to a suitable support bracket 79 which is, in turn, fastened to cross member 11 of framework 10. Gear box 77 is also provided with the usual input shaft 78 which will be further discussed hereinafter. Oscillatory gear boxes such as 77 are well known and such gear box will also be further discussed hereinafter in the description.

Carriage or sliding support member 65 carries a first fixed cam member 81 which extends between the left and right hand ends of member 65 as best illustrated in FIGS. 2 and 4. Cam member 81 is provided with a cam track or channel 82 extending substantially the length of the cam and having a curved configuration as shown in FIG. 4. There is secured to the bottom of cam member 81 below cam track or channel 82 a cam 83 (FIGS. 5 and 6) having a bottom surface such as shown in FIG. 7 and a planar configuration such as shown in FIG. 9, that is, a curved configuration similar to cam track or channel 82. The purpose of cam track or channel 82 and cam 83 will be discussed hereinafter in the description.

Sliding support member 65 also carries a second fixed cam member 86 which extends between the left and right hand ends of member 65 as best illustrated in FIG. 4. Cam member 86 is provided with a cam track or channel 87 extending substantially the length of the cam and having a curved configuration as shown in FIG. 4. There is secured to the bottom of cam member 86 below cam track or channel 87 a cam 88 (FIG. 8) having a bottom surface corresponding to that shown for cam 83 in FIG. 7 of the drawings and a planar configuration such as shown in FIG. 8, that is, a curved configuration similar to cam track or channel 86. The purpose of cam track or channel 87 and cam 88 will become apparent hereinafter in the description.

Sliding support member 65 includes a center portion 90 which extends between the ends of slide member 65 and embodies front and rear tracks or channels 91 and 92, respectively (FIGS. 4 and 5) which extend substantially the full length of said center portion 90. There is also included first and second shafts 93 and 94 which extend between the ends of slide member 65 adjacent the front and rear thereof, respectively. Shaft 93 slidably extends through bushings 95 and 96 provided on a first and front slide member 97 while shaft 94 slidably extends through bushings 98 and 99 provided on a second and rear slide member 100. Rollers or wheels 101 and 102 are rotatably mounted on the rear and front of slide members 97 and 100, respectively, and extend into the aforementioned track or channels 91 and 92, respectively, as shown in FIG. 4. First and second cam followers comprising rollers or wheels 103 and 104 are rotatably mounted on the tops of slide members 97 and 100, respectively, and each such cam follower is at times engaged in cam groove 27 of cam 25 in the manner and for the purpose discussed hereinafter in detail. Since slide members 97 and 100 are identical in structure, for purposes of simplification of the drawings, slide member 97 only is shown in detail therein. (See FIGS. 5 and 6 of the drawings). It will be readily recognized by those skilled in the art that slide member 100 is identical to slide member 97 but is horizontally rotated 180° in relation to the latter slide member.

Referring to FIGS. 5 and 6, slide member 97 comprises a main body member 106 on the top of which and in the front portion of which said cam follower 103, and said bushings 95 and 96 are provided, respectively. In relation to previously discussed fixed cam member 81 and parts 83 and 90 of such cam member, slide member 97 is vertically located as shown in FIGS. 5 and 6. Main body member 106 of slide member 97 has rear and front depending portions 107 and 108

between which a shaft 109 is supported. Body member 106 further includes depending rear and front portions 110 and 105, respectively, and a channel member 111, embodying a track or groove 112, extends between and is supported by such depending portions 105 and 110.

One end of a movable support 116 is provided with a pair of bushings or sleeves 117 and 118 through which the aforementioned shaft 109 extends in a snug but slideable relationship therewith. The second end of support 116 is provided with a wheel or roller 119 which is rotatably mounted on such second end and extends into track or groove 112 of channel member 111. Another roller or wheel 120 is rotatably supported on the bottom of member 116 and extends into the aforementioned cam track or channel 82 in cam member 81 for purposes hereinafter discussed. The upper end of a depending support member 126 is secured in any convenient manner to slideable support member 116, and a ribbon-length pickup head or device 170 is attached to the lower end of said member 126 in a manner which will be hereinafter described in connection with FIGS. 10 through 14, taken in conjunction with FIGS. 2, 3 and 5 of the drawings.

Referring now to FIGS. 2a, 2b and 2c taken in conjunction with FIGS. 1, 2, 4 and 5 of the drawings, a vertical plate member 131 is attached to the front face of previously discussed slide member 97 as by suitable screws or bolts such as 132 extending through the plate member and screwed into cooperative threaded holes provided in said face of slide member 97. There is secured to the front face of plate member 131 an arcuate member 136 having a curvature corresponding to that of sprocket wheel 47 as best illustrated in FIG. 2a. Arcuate member 136 is secured to plate member 131 as by screws such as 138. There is also secured to the front face of plate member 131, as by screws such as 142, a longitudinal vertical member 141. A pivoting member 144 is pivotally attached to the front face of plate member 131 as by a suitable screw 145. Arcuate member 136 is provided with a recessed portion 139 on its front face while member 141 is provided with a recessed portion 143 on its front face. The upper rear face of pivotal member 144 is provided with a recessed portion 147. When member 144 is in its position illustrated in FIGS. 2a or 2c the upper end of such member extends into recess 139 in member 136. Member 144 is normally biased to its position shown by a tensional spring 148 whose ends are connected to screws 149 and 150 screwed into cooperative threads provided in the lower ends of members 141 and 144.

As best illustrated in FIGS. 1 and 2b, the previously mentioned chain 51 carries on selected inner faces of its links a plurality of five rollers or wheels such as 133 which are rotatably mounted on suitable supports such as 134 on said faces of the selected links and which are equally spaced apart about the length of chain 51. The apparatus of FIGS. 2a, 2b and 2c, taken in conjunction with chain 51 and its associated rollers such as 133, provide slide member engagement means by which slide member 97 is at times engaged and, viewing FIGS. 1 and 4, moved in a direction from right to left along shaft 93 and along channel 91 of center portion 90 of sliding support member 65. This will be discussed in more detail hereinafter in an operational example of the apparatus of the invention.

As previously mentioned slide member 100 is identical to slide member 97 except that member 100 is horizontally rotated 180° from the orientation of member 97. Therefore, the items or devices designated by the reference characters 151, 156, 158, 161 and 166 shown in FIGS. 2, 3 and 4 of the drawings correspond, respectively, to items or devices 141, 126, 148, 131 and 136 discussed above in conjunction with slide member 97. Furthermore, in FIG. 1, chain 61, the rollers or wheels designated 153, and their associated supports designated 154 on chain 61, respectively correspond to chain 51, rollers or wheels 133, and supports 134 also shown in FIG. 1 as well as in other Figs. of the drawings discussed above in conjunction with slide member 97. Thus, the details of the structure of slide member 100 and its associated parts and devices will be readily apparent to those skilled in the art from the detailed description of the structure of slide member 97 and its associated parts and devices, and it will be readily recognized, therefore, that slide member 100 has associated therewith slide member engagement means by which such slide member is at times engaged and, viewing FIG. 4, moved in a direction from right to left along shaft 94 and along channel 92 of center portion 90 of sliding support member 65.

First and second ribbon-length pickup heads or devices 170 and 290 are shown in FIGS. 2, 3 and 4 of the drawings. Such pickup devices are identical to one another and, therefore, only device 170 is shown in the drawings in detail, such drawings comprising FIGS. 5 and FIGS. 10 through 14. However, it is pointed out that depending support member 156 (FIGS. 2 and 3) associated with ribbon-length pickup device 290 is carried by slide member 100 in a manner identical to that in which slide member 97 carries depending support member 126 previously described. Therefore, ribbon-length pickup device 290 is, similarly to the orientational relationship between slide members 97 and 100, horizontally rotated 180° in relationship to ribbon-length pickup device 170. This will be readily apparent to those skilled in the art.

Referring to FIGS. 5, 6, and 10 through 14, taken in conjunction with FIGS. 2, 3 and 4, pickup device 170 includes a pair of horizontally extending and parallel support bars 171 and 172 (FIGS. 10 and 12) which extend through suitable recesses such as 173 and 174, respectively, provided in the sides of a first support block 175. A second support block 176 is also provided and embodies recesses 183 and 184 (FIG. 5) similar to those in support block 175 and through which support bars 171 and 172 also extend. The bottom end of previously mentioned depending support member 126 is affixed, in any convenient manner, to the top surface of another support member 177 which includes at opposite ends thereof horizontally extending lug portions 178 and 179, and vertically extending lug portions 181 and 182. A third support block 186 (FIG. 2) is located between support blocks 175 and 176 and also includes recesses similar to 171, 172, 183 and 184 provided in support blocks 175 and 176, and through which support bars 171 and 172 also extend. However, the recesses in support block 186 are not shown in the drawings for purposes of simplification thereof. The top of support block 186 embodies a channel 187 in which is secured, in any convenient manner, a sliding

cam follower 188 having a curved top surface which at times slides along and against the bottom surface of cam 83 shown in FIG. 7 of the drawings and as hereinafter further discussed.

Referring to FIG. 14, support block 176 embodies a cavity 191 in which is disposed a short shaft 192 surrounded by a spring 193. The upper end of shaft 192 extends into a suitable hole extending vertically through lug portion 179 of member 177 and is secured therein by a pin 194 extending through suitable cooperative holes extending horizontally through such upper end and such lug portion. A hollow plug member 195 is provided in the lower part of cavity 191 in support block 176 and bears against the lower end of spring 193, such plug member being secured to the bottom end of shaft 192 by a screw 196 screwed into cooperative threads provided in the bottom end of shaft 192. Spring 193 is normally under compression, that is, is somewhat compressed in cavity 191 to normally maintain the upper surface of block member 176 against the lower surface of lug portion 179 of support member 177 as shown in FIG. 14. When parts of the pickup device 170, including the support bars 171 and 172, are actuated downwardly spring 193 is further compressed and permits such downward actuation. However, when the force actuating said parts downwardly is removed, spring 193 returns such parts, including support block 176, upwardly to their normal uppermost positions.

The structure of support block 175 is identical to support block 176 just described and the former support block includes a shaft 200 (FIG. 10) similar to shaft 192 associated with support block 176. Details of the internal arrangement of support block 175 and its associated parts are not shown in the drawings for purposes of simplification thereof but it is pointed out that the top surface of support block 175 is normally maintained against the lower surface of lug portion 178 of support 177 by a spring embodied in support block 175 and similar to spring 193 embodied in support block 176. This will be readily recognized by those skilled in the art from this brief discussion.

The center portion of a longitudinal torsion shaft or bar 201 extends snugly but rotatably through horizontally extending holes provided in lug portions 181 and 182 of support member 177. A first end of a lever arm 202 (FIGS. 10, 11 and 13) is securely clamped in any convenient manner to the left hand end of torsion shaft 201 (viewing FIG. 10) and the second end of lever arm 202 is provided with a rotatable wheel or roller 203 which extends into a suitable channel 204 provided in support block 205 as illustrated in FIGS. 10 and 13. Although not shown in the drawing it will be readily understood that block 205 includes a pair of recesses, similar to recesses 173 and 174 in block 175, and recesses 183 and 184 in block 176, through which support bars 171 and 172 extend for support of block 205. The aforesaid channel 204 in block 205 permits a limited amount of horizontal movement of roller or wheel 203 in block 205 but no vertical movement of such roller in such block.

A lever 207 (FIGS. 2 and 10) has a first end securely clamped to the right hand end of torsion bar or shaft 201 and its second end is provided with a rotatable wheel or roller (not shown) which extends into a chan-

nel (also not shown) provided in another support block 208 which is also supported by support bars 171 and 172 in the manner discussed in conjunction with block 205. It is pointed out that the arrangement of block 208 and its associated parts is similar to that of block 205 and its associated parts except of the opposite hand and, therefore, further details of block 207 and its associated parts are omitted from the description for purposes of brevity. However, it is pointed out at this point in the description that torsion bar or shaft 201, levers 202 and 207, and blocks 205 and 208 provide a stabilizing arrangement for pickup device 170, that is, an arrangement by which torsion is supplied to torsion shaft 201 at the left and right ends thereof, and in opposite directions, when pickup device 170 reaches the limits of left and right hand ends of its path of movement hereinafter discussed. Such torsion shaft arrangements are well known to those skilled in the art.

20 A first pair of ribbon-length positioning devices 211 and 212 (FIGS. 2, 5, 11 and 13) are supported on the ends of a horizontal yoke member 213 which is secured in any convenient manner to the lower end of a support 214 whose upper end extends into a suitable cavity 215 (FIG. 13) provided in the previously discussed support block 205. A compressional spring 216 is also provided in cavity 215 and its ends bear against the wall defining the limits of the upper end of cavity 215 and the upper end of support 214. Spring 216 normally biases support 214 downwardly in cavity 215. A pin 217 extends into a vertical slot 218 provided in support 214 and limits the downward movement of support 214 in cavity 215. However, support 214 can be moved upwardly in cavity 214 a distance corresponding to the vertical height of slot 218. The ribbon-length positioning devices 211 and 212 embody in their lower ends conical shaped cavities 221 and 222, respectively, which cooperate with conical projections such as 223 and 224 shown by dotted lines in FIG. 5 as extending upwardly from the upper surface of a length of ribbon such as 225 supporting a depending article such as 226 and which the apparatus of the invention is intended to handle. The cavities such as 221 and 222 and the associated projections such as 223 and 224 are intended to cooperate with each other to correctly position a length of ribbon such as 225 in relation to pickup device 170.

40 A second pair of ribbon-length positioning devices 231 and 232 (FIGS. 2 and 12) are supported on the ends of a horizontal yoke member 233 which is secured in any convenient manner to the lower end of a support 234 whose upper end extends into a suitable cavity provided in the previously discussed support block 208. The internal arrangement of block 208 is similar to that discussed for block 205 except of the opposite hand and, therefore, no detailed description of the parts embodied in block 208 is considered necessary for those skilled in the art. However, it is pointed out that ribbon-length positioning devices 231 and 232 embody in their lower ends conical shaped cavities 241 and 242 which are intended for the same purpose previously described in conjunction with cavities 221 and 222 provided in ribbon-length positioning devices 211 and 212.

60 Ribbon-length pickup device 170 further includes a pair of parallel shafts 246 and 247 which are (viewing FIGS. 2, 4 and 10) supported at their left and right hand ends by left hand and right hand end pieces 248

and 249, respectively, through which shafts 246 and 247 snugly but rotatably extend. End pieces 248 and 249 are secured to the ends of previously mentioned support bars 171 and 172, and are supported by such support bars. First ends of a plurality of pickup finger support members such as 251 and 252 shown in FIGS. 3, 4, 5, 10, 11 and 12 are securely clamped in an obvious manner about shafts 246 and 247 at spaced intervals therealong as will be readily apparent. There is affixed to the lower end of each of the finger support members such as 251 and 252 the upper end of an L-shaped pickup finger such as 253 and which is preferably made of a somewhat flexible material such as a leaf spring material. It is pointed out that the pickup fingers such as 253 and their support members are omitted from FIG. 2 of the drawings for purposes of clarity of such drawing figure.

One end of each of a pair of lug or crank members 256 and 257 surround shafts 246 and 247, respectively, adjacent the left hand ends thereof as shown in FIGS. 2, 4, 10 and 11, such lug members being affixed to such shaft, in any convenient manner, for rotational movement with the shaft. There is pivotally joined to the second ends of lug or crank members 256 and 257 a linking arm 258 as best shown in FIG. 11. By such arrangement any rotation of shaft 246 causes equal but opposite rotation of shaft 247, and any rotation of shaft 247 causes equal but opposite rotation of shaft 246 as is readily apparent. Shafts 246 and 247 are provided adjacent the right hand ends thereof with an arrangement similar to that just described and including lug or crank members 259 and 260 (FIG. 10) whose first ends surround and are affixed to shafts 246 and 247, respectively. A linking arm 261 is pivotally connected to the second ends of crank members 259 and 260, and the rotation of one of the shafts 246 or 247 imparts, through linking arm 261, equal but opposite rotation of the other of such shafts.

One end of a first pressurized fluid cylinder 266 (FIGS. 4, 5, 10 and 11) is provided with a lug 267 whose otherwise free end is pivotally attached to a cross member 268 which is in turn affixed to the top surfaces of support bars 171 and 172 in any suitable manner. The otherwise free end of piston rod 269 of fluid cylinder 266 is provided with a suitable bearing member 270 which is disposed between the branches of a bifurcated member 271 and is pivotally connected thereto. Bifurcated member 271 is clamped at its lower end to shaft 247 in any suitable manner and, thus, any motion imparted to piston rod 269 by the piston of cylinder 266 causes rotational movement of shaft 247. There is connected to the front and rear ends of cylinder 266 (FIGS. 2, 4 and 11) first and second pressurized fluid conduits 272 and 273, respectively, through which pressurized fluid is supplied to cylinder 266 for actuation of a length of piston rod 269 into and out of cylinder 266 as hereinafter discussed in an operational example of the invention.

One end of a second pressurized fluid cylinder 276 (FIGS. 4 and 12) is provided with a lug 277 whose otherwise free end is pivotally attached to a cross member 278 which is in turn affixed to the top surfaces of support bars 171 and 172 in any suitable manner. The piston rod 279 of fluid cylinder 276 is provided with a suitable bearing member 280 which is disposed

between the branches of a bifurcated member 281 and is pivotally connected thereto. Bifurcated member 281 is clamped at its lower end to shaft 246 in any suitable manner and, thus, any motion imparted to piston rod 279 by the piston of cylinder 276 causes rotational movement of shaft 246. There is connected to first and second ends of cylinder 276 first and second pressurized fluid conduits 282 and 283, respectively, through which pressurized fluid is supplied to cylinder 276 for actuation of a length of piston rod 279 into and out of cylinder 276 as also hereinafter discussed in an operational example of the invention.

As previously mentioned, ribbon-length pickup head or device 290 (FIGS. 2, 3 and 4) is identical to pickup device 170 just described except that device 290 is horizontally rotated 180° from the orientation of device 170. Thus, parts 291, 295, 296, 297, 306, 311, 312, 317, 318, 321, 324, 331, 334, 336, 337, 338, 339, 341, 343, 346 through 351, 356 through 363, 366 through 370, 372, and 373 of device 290 shown in FIGS. 2, 3 and 4 correspond respectively to parts 171, 175, 176, 177, 186, 201, 202, 207, 208, 211, 214, 231, 234, 246, 247, 248, 249, 251, 253 through 261, 266 through 273, 276, through 280, 282 and 283 of device 170 shown in the drawings.

Referring to FIGS. 24 and 25 of the drawings taken in conjunction with FIGS. 1, 2 and 3, there is shown a ribbon-length receiving and transfer means located adjacent said exit end of the previously mentioned handling station and which receives each ribbon-length handled by the apparatus of the invention, and transfers or conveys each such ribbon-length away from the handling station to another location where additional operations may be performed on the articles, such as the ribbon lengths and/or the pendent articles or bodies depending therefrom. The ribbon-length transfer means comprises a gang or plurality of parallel, equally spaced-apart and relatively narrow conveyor belts such as 376 and 377 which are not shown in FIG. 25 for purposes of clarity of such drawing figure. The loop of travel of conveyor belts such as 376 is shorter than that of conveyor belts such as 377 and, therefore, conveyor belts such as 377 extend, as best illustrated in FIG. 3, a greater distance under the previously described ribbon-length pickup devices 170 and 290.

Each conveyor belt such as 376 loops about pulleys such as 378 and 379 suitably and rotatably supported on an associated support plate such as 380 as illustrated in FIGS. 2, 3 and 24 of the drawings. Each respective conveyor belt such as 376 rides along the surface of the upper edge of its respectively associated support plate such as 380, such plate thus giving support to its respective conveyor belt in addition to that provided by the tension of the belt alone. Similarly, each conveyor belt such as 377 loops about pulleys such as 381 and 382 suitably rotatably supported on an associated support plate such as 383 as also illustrated in FIGS. 2, 3 and 24 of the drawings. Each respective conveyor belt such as 377 rides along the surface of the upper edge of its respectively associated support plate such as 383 for the same purpose as that mentioned in conjunction with the conveyor belts such as 376.

For purposes of simplification of the drawings only the left hand ends (viewing FIGS. 3 and 24) of the conveyor belts such as 376 and 377 are shown in the

drawings but the arrangement of such belts will be readily apparent to those skilled in the art from the brief foregoing description thereof. In operation, the conveyor belts are moved in the direction indicated by the arrows in FIGS. 3 and 24, such belts being so moved by any suitable driving means not shown but which are well known in the art. The speed of movement of the conveyor belts such as 376 and 377 is not critical but must be such that a preceding ribbon-length such as 225 deposited on or received by the conveyor belts (FIGS. 1, 3, 24 and 25) is moved to clear the next succeeding ribbon-length to be similarly deposited on the conveyor belts, as is believed obvious. It is pointed out that the ribbon lengths such as 225 shown in the drawings are illustrated as supporting a plurality of pendent articles or bodies such as 226 having the configuration of jars or food containers as previously mentioned.

As best shown in FIGS. 24 and 25, the ribbon-length receiving and transfer or conveying means further includes a gang or plurality of ribbon-length supporting devices such as 386 having sloping lower portions such as 387 and horizontally extending upper portions such as 388 which receive or take on their upper surfaces each ribbon length such as 225 handled by the apparatus. The lower ends of the devices such as 386 are secured, as by welding for example, to a cross member 389 which is, in turn, similarly affixed or secured to upwardly extending extensions 390 and 391 of first and second links or linking members 392 and 393, respectively. The upper end of links 392 and 393 extend between bifurcations provided on the upper ends of first and second supporting arms 394 and 395, respectively, and are pivotally connected thereto. The lower ends of bifurcated or forked supporting arms 394 and 395 are connected to the ends of an axle or shaft 405 rotatably supported in the upper ends of upright pedestals or posts 396 and 397, respectively, whose lower ends are affixed to a base 398 which may, for example, rest on the previously mentioned platform or floor 20.

An oscillatory gear box 399 is also mounted on base 398 and includes an oscillatory output shaft 400 to which are attached first ends of first and second crank arms 402 and 403 having bifurcated second ends to which is pivotally connected the lower ends of previously mentioned links or linking members 392 and 393, respectively. A suitable gear reduction box 404 is mounted on the top of gear box 399 and includes a power input shaft 406 which is suitably connected to a power train as hereinafter pointed out. The output shaft of gear box 404 is, of course, not shown in the drawings since it extends downwardly through the bottom of gear box 404 and the top of gear box 399 to supply power to the latter gear box and cause oscillatory motion of output shaft 400 which, in turn, oscillates arms 394 and 395, links 392 and 393, and crank arms 402 and 403 between their positions illustrated by the solid and dotted lines shown in FIG. 24. Such oscillatory movement, in turn, correspondingly actuates cross member 389 and ribbon-length supporting devices such as 386 between their lowered and raised positions also illustrated by solid and dotted lines in FIG. 24. This will be discussed in more detail hereinafter in an operational example of the invention.

Referring again to FIG. 1, but now taken in conjunction with FIGS. 15 through 21, there is shown a conveyor generally indicated by the reference character 410 and intended for conveying the previous discussed ribbon of a thermoplastic material, or cracked-off ribbon lengths of such ribbon, through at least a part of a so-called second path of travel which extends generally collinear with a first or selected path of travel to be hereinafter discussed. Such second path of travel extends to an entrance end of a handling station intermediate the ends of such second path, and through such station or intermediate location to an exit end thereof and thence beyond such exit end to a selected location where the path of travel terminates. In other words conveyor 410 comprises an endless looped conveyor which extends through an obround path of travel, such path having an entrance end adjacent an exit end of a first or preceding path of travel and then extending through a first location, to be hereinafter discussed, and then through a second location at which a ribbon length handling station having entrance and exit ends is located. Said obround path of travel then extends from the exit end of the handling station to a selected location beyond such exit end where conveyor 410 then loops to return to said entrance end of the obround path of travel.

Conveyor 410 is supported by the upper ends of upright supports or legs designated 411 and 412 (FIGS. 1, 15, 16, 17, 18, 21, 22 and 23) whose lower ends are not shown in the drawings but which may rest, for example, on the platform or floor 20 previously mentioned. Referring to FIGS. 15, 17, 18 and 21, there is shown affixed to leg 411 upper and lower support brackets 413 and 414, respectively, and to leg 412 upper and lower support brackets 416 and 417, respectively. Brackets 413 and 416 support on their upper surfaces a hollow beam 418 which is affixed to such surfaces and extends for a substantial part of the length of conveyor 410. There is secured to the front face of beam 418 a rail member 419 which extends for the length of beam 418 and at the right hand end of conveyor 410 (viewing FIG. 21) extends somewhat beyond the end of beam 418. There is also affixed to legs 411 and 412 a second rail member 420 whose lower edge rests on and is also secured to beam 418, and which embodies a track or groove 421 whose purpose will hereinafter be discussed along with the above mentioned rail member 419. Rail member 420 extends for a distance corresponding to the length of rail member 419.

A hollow beam 426 rests on the top surfaces of brackets 414 and 417, and is affixed thereto. Beam 426 also extends for a substantial part of the length of conveyor 410 as illustrated in FIGS. 15 and 21. A longitudinal relatively thin plate 427 is secured to the top of beam 426 and a pair of spaced-apart longitudinal strip members 428 and 429 are secured to the top surface of plate 427 as best shown in FIG. 18. Plate 427 extends for the full length of the top surface of beam 426 while the right hand ends of strips 428 and 429 stop short of the right hand end of the top surface of plate 427 (viewing FIG. 21). Said right hand ends of strips 428 and 429 meet with the lower end of a curved track or rail member 431 embodying in its front face a track or groove 432 whose upper end precisely joins with the

previously mentioned track or groove 421 embodied in the previously mentioned second rail member 420. The purpose of track or groove 432 will also be further discussed hereinafter. It is now pointed out, however, that the top surface of plate 427 provides a runway for rollers or wheels hereinafter discussed, while the space between strip members 428 and 429 provides a track or groove for certain ones of such rollers or wheels as also discussed hereinafter.

Viewing FIG. 15, taken in conjunction with FIG. 19, the left hand end of the previously mentioned second rail member 420 abuts against the right hand end of a third rail member 436 which embodies a track or groove 437 whose right hand end precisely joins with track or groove 421 embodied in rail member 420. Track or groove 437 (moving from right to left through member 436) twists 90° in a left hand direction, that is to say, groove 437 twists so that the back wall of groove 437 twists 90° to the left from a vertical attitude to a horizontal attitude as best illustrated in FIG. 19.

Now further viewing FIG. 15, taken in conjunction with FIG. 20, the left hand end of the previously mentioned plate 427, and strip members 428 and 429, meet with the right hand end of a fourth rail member 438 which embodies a track or groove 439. Track or groove 439 (moving from right to left through member 438) twists 90° in a right hand direction, that is to say, groove 439 twists so that the back wall of groove 439 twists 90° to the right from a vertical attitude to a horizontal attitude as best illustrated in FIG. 20.

A curved rail or track member 440 (FIGS. 15 and 16) is provided with a groove or track 441 which corresponds in cross section to track or groove 421 in rail member 420. Groove or track 441 extends about the inner periphery of the curved rail or track member 440 with the opening into the track or groove 441 facing the center of the curve of the rail or track member 440 as best illustrated in FIG. 15. The upper and lower ends of member 440 abut against the left hand ends of rail members 436 and 438, respectively, and the upper and lower ends of the track or groove 441 in rail member 440 precisely join with the left hand ends of the tracks or grooves 437 and 439, respectively, in upper and lower rail members 436 and 438, respectively.

A support plate 442 (FIGS. 1, 15 and 16) is supported adjacent the upper end of leg 411 by a bracket member 443 which is attached, as by welding for example, to the back face of plate member 442 and to the left hand side (viewing FIG. 1) of leg 411. The previously discussed rail or track members 436 and 438 are secured to the front face of supporting plate 442 and are thus supported thereby. First ends of a plurality of three brackets 443, 444, and 445 are also affixed, as by welding, to the front face of support plate 442 and the second ends of such brackets are similarly affixed to rail member 440 and support such member in the attitude previously discussed. An idler sprocket wheel 446 is rotatably mounted on the front face of support plate 442 by a suitable axle or shaft 447 which is fastened to the support plate.

Referring further to FIGS. 1 and 21, a support plate 448 is supported adjacent the upper end of leg 412 by a bracket member 450 which is attached, as by welding for example, to the back face of plate 448 and to the right hand side (viewing FIG. 1) of leg 412. The previ-

ously discussed curved rail or track member 431 is secured to the front face of support plate 448. An axle or shaft 449 is rotatably supported on the front face of plate 448 and a first sprocket wheel 451 is keyed to the front end of shaft 449 while a second sprocket wheel 452 is keyed to the rear end of such shaft. A drive chain 453 loops about sprocket wheel 452 and a smaller drive sprocket 455 which is keyed to the output shaft of a suitable gear box 454. When rotational power is supplied to the input shaft 456 (FIG. 1) of gear box 454 as hereinafter described, sprocket wheel 455 is rotated to drive chain 453 which in turn drives sprocket wheel 452 to, thereby, cause rotation of sprocket wheel 451 in a clockwise direction as indicated by the arrow thereon in FIG. 21. The arrangement just discussed will be readily apparent to those skilled in the art from this brief description thereof.

Conveyor 410 further includes a conveyor chain 458 (FIGS. 15, 17 and 18) which loops about sprocket wheel 451, just discussed, and previously discussed idler sprocket wheel 446 shown in FIGS. 15 and 16. For purpose of simplification of the drawings, the full length of chain 458 is not shown in detail in the drawings but its obround looped path is indicated by dotted lines shown in FIGS. 15 and 21, as is believed obvious. There is attached to each of selected links of chain 458 a carrier block such as 459 (FIGS. 15 through 18) such carrier blocks being equally spaced apart along the length of the chain as illustrated in FIG. 15 but only a few of which blocks are shown in the drawings for purposes of simplification thereof. There is pivotally attached to each carrier block such as 459 a carriage member such as 460 each of which rotatably supports on its ends first and second wheels or rollers such as 461 and 462 which are mounted on axles such as 463 and 464, respectively. Each axle such as 464 has attached to the otherwise free end thereof a ribbon support arm such as 465.

It is believed that it will be expedient at this point in the description to give a brief operational example of conveyor 410 and its chain 458 and the other associated parts just described.

It is assumed that sprocket wheel 451 is being rotated in a clockwise direction as indicated by the arrow on such wheel in FIG. 21. Chain 458 is, therefore, being driven in the directions indicated by the arrows in FIG. 15 and the parts comprising the carrier blocks such as 459, carriage members such as 460 and their associated rollers or wheels such as 461 and 462, and the ribbon support arms such as 465 are being correspondingly moved by chain 458. The wheels or rollers such as 461, moving along the upper part of the looped path of travel of chain 458, ride in channel or track 421 at such time (FIG. 17) while wheels or rollers such as 462 roll along on the top surface of rail 419. The wheels or rollers such as 461 and 462 moving along the lower part of the looped path of travel of chain 458 roll along on the top surface of plate member 427 with the wheels such as 461 being between the strip members 428 and 429 (FIG. 18). As each wheel or roller such as 461 moves along said lower part of said looped path of travel and reaches rail or track member 438, it enters track or groove 439 in such rail member and the respective carriage member such as 460 pivots on its associated carrier block 459 as the respective wheel or roller such as

461 proceeds through track or groove 439. At the exit end of such track or groove the respective carriage member such as 460 and its associated ribbon support arm such as 465 are in a vertical attitude when said wheel 461 enters track or groove 441 in curved rail or track member 440. The attitude of each respective carriage member and associated ribbon support arm, as each respective wheel such as 461 proceeds along the curved track or groove 441 in member 440, will be apparent from a brief glance at FIGS. 15 and 16 of the drawings.

Following the passage of each respective wheel 461 through groove or track 441 in curved track member 440, each such wheel moves into the left hand end of groove or track 437 in upper track or rail member 436. During the passage of each wheel such as 461 through track or groove 437, each respective carriage member such as 460 and its associated ribbon support arm such as 465 changes from a vertical attitude to the horizontal attitude shown in FIG. 17, and the respective wheel such as 463 moves into track or groove 421 in rail or track member 420. By such apparatus arrangement each ribbon support arm such as 465 is moved upwardly between a pair of adjacent pendent articles or bodies such as 226 depending from a parent ribbon 10 moving from left to right (FIG. 1) to the handling apparatus of the invention. Such apparatus arrangement and operation assures that the ribbon support arms such as 465 do not contact the pendent articles or bodies such as 226 as such arms move into position under the ribbon 10 to support same and convey it and said depending articles or bodies to the handling apparatus of the invention.

With reference to FIGS. 22, 22a through 22f, 23, 23a and 23b, the ribbon-length crack-off, or fracturing apparatus or means which breaks ribbon 10 into substantially equal ribbon lengths such as 225 each of which supports the same number of pendent articles or bodies such as 226 will be discussed. However, it is first pointed out that ribbon 10, preferably during the forming thereof, is provided with break-off or crack-off locations comprising channels or grooves such as 470 (FIGS. 1, 22a and 22c). Ribbon 10, during the forming thereof, is also provided on its top surface with the previously mentioned projections such as 223 and 224 (FIGS. 1, 5, 22a and 22b). The channels or grooves such as 470 in ribbon 10 may, for example, be provided in such ribbon by a knife-edge or wedge-shaped protrusion similar to that shown on forming roll 134 shown in FIG. 13 of copending patent application, Ser. No. 813,534 filed Apr. 4, 1969 by Roy N. Sundstrom et al. for Method of and Apparatus For Forming Glass Parisons. Such copending application is assigned to the same assignee as the present application. The projections such as 223 and 224, provided on ribbon 10 shown in the drawings of the present application, can be formed in such ribbon by suitably shaped cavities embodied in the outer peripheral surface of a forming roll similar to said roll 134 of said copending application. It is pointed out, however, that a forming roll similar to roll 134 of the copending application and used for forming the ribbon such as 10 would embody a plurality of eight pockets rather than six pockets such as 138 shown in said FIG. 13 of the cited copending application. This is because the apparatus of the present

invention is shown and described as handling ribbon-lengths such as 225 each having a plurality of eight pendent articles or bodies such as 226. This will be readily apparent to those skilled in the art.

5 The ribbon-length crack-off or fracturing apparatus or means is designated generally in FIGS. 22, 23, 23a and 23b, by the reference character 475. Such apparatus is omitted from FIGS. 1 and 3 of the drawings for purposes of clarity of such drawings. However, a location for the fracturing apparatus such as 475, in relation to conveyor 410 previously discussed and as an example of the actual practice of the present invention, is illustrated generally in FIG. 22 by the dotted-line outline of conveyor 410 and its supporting leg 411. It is further pointed out, however, that conveyor 410 may be of any reasonable maximum length and that the fracturing apparatus or means such as 475 can be located at any convenient location between the left hand end of conveyor 410 as illustrated in FIG. 22 and the left hand end of the main portion of the article handling apparatus shown in FIG. 1 and previously described.

20 Referring now to FIGS. 22, 23, 23a and 23b in detail, the ribbon crack-off or fracturing apparatus 475 includes first and second support members or legs 476 and 477 having secured thereto, adjacent the upper ends of the legs, first and second brackets 478 and 479, respectively, which extend outwardly from their 25 respectively associated legs a substantial distance and in a direction generally paralleling conveyor 410. Although not shown in the drawings, it is pointed out that the lower ends of legs 476 and 477 may rest on the platform or floor such as 20 previously discussed.

30 35 Supporting pedestals such as 480 and 481 are mounted on the upper ends of legs 476 and 477, respectively, and a pair of other pedestals such as 482 and 483 are mounted on the upper surface of the right hand ends (viewing FIG. 22) of brackets 478 and 479, respectively. First and second support frames such as 485 and 486 are secured to pedestals 480 and 482, respectively, at the left and right hand ends, respectively, of the break-off apparatus (viewing FIG. 22). Another pair of support frames such as 487 and 488 are secured to pedestals 481 and 483, respectively (FIGS. 23a and 23b). Support frame 488 includes upper and lower outwardly extending portions such as 490 and 491 (FIG. 23) which help support upper and lower longitudinal rail or track members such as 492 and 493, respectively, embodying tracks or channels 494 and 495, respectively. Support frame 486 (FIGS. 22 and 23) includes upper and lower outwardly extending portions such as 496 and 497, respectively, which help support upper and lower longitudinal rail or track members such as 498 and 499, respectively. Track or rail members 498 and 499 embody tracks or channels 500 and 501, respectively.

40 45 50 55 60 Support frame 485 includes upper and lower outwardly extending portions such as 502 and 503, respectively (FIG. 22) which help support the above mentioned rail or track members 498 and 499, respectively. Support frame 487 (FIG. 23b) helps to support rail or track members 492 and 493 (FIG. 23) in a manner similar to that in which frame 485 aids in supporting rail or track members 498 and 499, as will be readily apparent to those skilled in the art. Frame member 485

further includes another pair of upper and lower outwardly extending portions 504 and 505 which support the left hand ends (viewing FIG. 22) of rail or track members 498 and 499, respectively. Said portions 504 and 505 also support the ends of a curved track or rail member 506 which embodies a curved track or channel 507 whose upper and lower ends precisely join with the left hand ends (viewing FIG. 22) of the channels or tracks 500 and 501, respectively, embodied in rail or track members 498 and 499. Frame member 487 supports a curved track or rail member 508 which is similar to member 506 but of the opposite hand, and which embodies a curved track or channel whose upper and lower ends precisely join with the left hand ends of the channels or tracks 494 and 495, respectively, embodied in rail or track members 492 and 493.

Returning to the right hand end of the apparatus as shown in FIG. 22, frame member 486 further includes another pair of upper and lower outwardly extending portions 511 and 512 which support the right hand ends of rail or track members 498 and 499, respectively. Said portions 511 and 512 also support the ends of a curved rail or track member 513 which embodies a curved track or channel 514 whose upper and lower ends precisely join with the right hand ends of the channels or tracks 500 and 501, respectively, embodied in rail or track members 498 and 499. Frame member 488 (FIGS. 23 and 23a) at the right hand end of the machine further includes another pair of upper and lower outwardly extending portions 516 and 517 (FIG. 23a) which support the right hand ends of rail or track members 492 and 493, respectively. Said portions 516 and 517 also support the ends of a curved track or rail member corresponding to track or rail member 513 but of the opposite hand, and embodying a curved track or channel similar to track or channel 514 embodied in said member 513 (FIG. 22). The right hand ends of the tracks or channels such as 494 and 495 embodied in members 492 and 493, respectively, precisely join with the upper and lower ends, respectively, of the curved track or channel embodied in said curved track or rail member supported by portions 516 and 517 of frame member 488. This latter curved track or rail member is omitted from the drawings for purposes of simplification thereof, but its arrangement will be readily apparent by the brief foregoing discussion thereof taken in conjunction with FIGS. 22 and 23a of the drawings.

In FIGS. 22 there is shown at the left end of apparatus 475 a first pair of support brackets 540 and 541 having first ends which are affixed, as by welding for example, to curved rail or track member 506. The second ends of brackets 540 and 541 are similarly affixed to a curved cam member 542 for support of such cam member adjacent the left hand end of the apparatus (FIGS. 22 and 23b). Cam member 542 has an outer periphery 543 whose outer surface is contacted by sets of rollers or wheels to be hereinafter discussed and which at times roll about said outer periphery. There is further shown in FIG. 22 at the right hand end of the apparatus 475 a second pair of support brackets 544 and 545 having first ends affixed, as by welding, to curved rail or track member 513. The second ends of brackets 544 and 545 are similarly affixed to another curved cam member 546 for support of such cam member adjacent the right hand end of the apparatus

(FIGS. 22 and 23a). Cam member 546 has an outer periphery 547 whose outer surface is contacted by said sets of rollers or wheels and which at times roll about said outer periphery.

5 Another pair of curved cam members 547 (FIG. 23a) and 548 (FIG. 23b) similar to curved cam members 542 and 546, and supported in a manner similar to that in which the latter cam members are supported, are provided at the right and left hand ends, respectively (viewing FIG. 22) of apparatus 475 but at the rear thereof and therefore not shown in FIG. 22. However, it is pointed out that cam members 547 and 548 perform the same functions as their counterparts 542 and 546.

15 At the left hand end of apparatus 475 (viewing FIGS. 22 and 23b) a pair of roller guide members such as 550 and 551 are secured to curved cam members 542 and 548, respectively. Such guide members provide tracks or channels 552 and 553, respectively, which receive the previously mentioned rollers or wheels which roll about and along the outer peripheries of curved cam members 542 and 548, respectively. At the right hand end of apparatus 475 (viewing FIGS. 22 and 23a) a pair 20 of roller guide members such as 556 and 557 are secured to curved cam members 546 and 547, respectively, which receive the previously mentioned rollers or wheels which roll about and along the outer peripheries of curved cam members 546 and 547, respectively.

25 There is also secured to support frame 488 a gear box 520 shown in cross section in FIGS. 23 and 23a, and including a vertical input shaft 521 and a horizontal output shaft 522, both such shafts being supported in gear box 520 by suitable bearings such as 523 through 528 and the ends of such shafts within gear box 520 being connected with each other by a set of bevel gears 529 and 530 as is well known. It will be understood that the second end 531 of shaft 521 is connected to a suitable power train by which rotational movement in the direction indicated by the arrow adjacent said ends 531 is imparted to shaft 521. The second end of shaft 522 is supported in bearings such as 532 and 533 suitably disposed in a sleeve member 30 35 suitably supported by support frame 486. First and second sprocket wheels 535 and 536 (FIGS. 22, 23 and 23a) are keyed to shaft 522 for driven rotation therewith, such wheels being maintained in a spaced-apart relationship with each other by a sleeve member 40 45 537. The purpose of sprocket wheels 535 and 536 will be discussed hereinafter.

50 Referring now to FIGS. 22, 23, 23a and 23b taken in conjunction with FIGS. 22a through 22f, there is shown a plurality of similar blowheads each of which is designated generally by the reference character 560. Such blowheads are spaced on centers corresponding to the spacing between the centers of the pendent articles or bodies such as 226 depending from a parent ribbon such as 10. Since the present invention is illustrated and described as handling ribbon lengths such as 225, each of which supports a plurality of eight pendent articles or bodies such as 226, the number of the plurality of blowheads such as 560 carried by the apparatus such as shown in FIGS. 22, 22a, 23, 23a and 23b should, for purposes hereinafter set forth, be some multiple of eight and, therefore, a plurality of thirty two blowheads such as 560 has been arbitrarily chosen for

the ribbon-length break-off or fracturing apparatus or means shown in FIGS. 22, 22a, 23, 23a and 23b of the drawings.

Referring to FIGS. 22, 22a through 22c, 23, 23a and 23b, each blowhead such as 560 comprises a cylindrical main body or sleeve member such as 561 which is carried by a carriage member such as 562 (FIGS. 22a, 23, 23a and 23b) each of which is pivotally linked on both sides thereof to the carriage members carrying the adjacent sleeve members as best illustrated in FIG. 22a. Each carriage member such as 562 is provided on a first side thereof with a pair of wheels or rollers such as 563 and on the opposite side thereof with a pair of rollers such as 564 (FIGS. 23 and 23a). Each roller such as 563 is common to two adjacent carriages since it is rotatably mounted on the pivot means pivotally linking adjacent carriage members. Similarly, each roller such as 564 is common to two adjacent carriages since it is rotatably mounted on the pivot means pivotally linking adjacent carriage members. The rollers such as 563 and 564 are spaced from their respectively associated carriage members by spacer means such as 565 and 566, respectively, which are provided for a purpose hereinafter discussed. The rollers or wheels such as 563 travel in tracks or channels 500, 501, 507 and 514 embodied in track or rail members 498, 499, 506 and 513, respectively. The rollers or wheels such as 564 travel in tracks or channels 594 and 495 embodied in track or rail members 492 and 493, respectively, and also travel in the previously discussed tracks or channels embodied in curved rail member 508 and the corresponding rail member provided on the rear of the right hand end of apparatus 475 (viewing FIG. 22).

The blowheads such as 560 each include, on one end thereof, a member such as 567 which makes sliding contact with the bottom surface of a blowbox such as 568 to receive pressurized cooling air therefrom in the manner well known in the art (FIGS. 22, 22a, 23, 23a and 23b). The second ends of the blowheads such as 560 each include the usual blowtips such as 569 which are at times actuated into the openings into the pendent bodies or articles such as 226 depending from ribbon 10. A ribbon hold-down plate such as 570 is positioned on each of the blowheads such as 560 adjacent the blowtip on the respective blowhead and each plate such as 570 contacts the upper surface of ribbon 10 when the respectively associated blowtip such as 569 is in an opening into one of the bodies or articles such as 226, as mentioned above.

A yoke member such as 572, including a circular disk-like center portion 573 and two extending arm portions 574 and 575, is secured to each blowhead such as 560 between the sleeve member such as 561 and the hold-down plate such as 570 of the respective blowhead. A roller or wheel such as 576 is rotatably mounted on the end of arm portion 574 of each respective yoke member such as 572, and a roller or wheel such as 577 is similarly rotatably mounted on the end of arm portion 575 of each respective yoke member such as 572. The rollers of wheels such as 576 are, for example, those which roll about the outer peripheries 543 and 547 of curved cam members 542 and 546, respectively, as previously mentioned. The rollers or wheels such as 577 are, for example, those which roll about the outer peripheries of curved cam members 547 and 548,

respectively, as also previously mentioned. The purpose of the rollers or wheels such as 575 and 576 will be further discussed hereinafter. It is, however, believed expedient to point out at this point in the description that the blowtips such as 569, the hold-down plates such as 570, the yoke members such as 572 and their associated rollers such as 576 and 577 are all normally spring biased upwardly along with their support members such as 578 which extend into the sleeve member such as 561 of each blowhead such as 560, each such sleeve member housing a suitable spring for providing such biasing as is well known in the art. It is also pointed out that, as is also well known in the art, a cooling air passage extends through the length of each blow-head such as 560 to at times convey cooling air from blowbox 568 to blowtip 569 of the respective blowhead. It is further pointed out, with reference to FIGS. 22, 22a, 23 and 23a, that the previously mentioned linked carriage members such as 562 and the blowheads such as 560 and their associated parts are, as hereinafter further discussed, moved through a looped obround path of travel indicated generally in FIG. 22 by the broken line defining an obround configuration and designated by the reference character 580. Such movement of the ribbon-length break-off or fracturing apparatus is provided by the previously described sprocket wheels 535 and 536 which are driven, as previously described, in a counter-clockwise direction (viewing FIG. 22) as indicated by the broken line arrow on sprocket 535. The previously mentioned spacer means such as 565 and 566 protrude into the spaces between the teeth of sprocket wheels 535 and 536, respectively, as each respective pair of such spacer means moves past the respective sprocket wheels, and the teeth of the sprocket wheels thereby impart movement to said spacer means and, thereby, the aforesaid movement of the apparatus through said looped path of travel designated 580.

There is shown in FIG. 22, at the lower center portion of looped path of travel 580, a group of three of the blowheads such as 560, the center one of which is provided with a ribbon fracturing or ribbon-length break-off means 601 and the end ones of which group are provided with orienting or positioning means 581 associated with said fracturing means. Referring to FIG. 22a, only the left hand one of the positioning means such as 581 is shown in detail since the right hand one of such means is identical to the left hand one (viewing FIG. 22).

Referring to FIG. 22a, taken in conjunction with FIG. 22, the positioning means such as 581 comprises a support such as 582 which is secured to the previously mentioned yoke such as 572 as by suitable bolts such as 583 (FIG. 22a). The support such as 582 has downward extending arms such as 584 and 585 (FIG. 22b) between which extends the rear portion 587 of a pivoting member 586, such rear portion 587 being pivoted between said arms by a pivot pin such as 588.

The ribbon contacting device 591, per se, of positioning means 581 comprises an upper part 589 which is secured to the front portion of pivoting member 586 as by suitable bolts such as 590. Device 591 further includes downwardly extending arms or projections such as 592 and 593 which embody recesses or cavities such as 594 and 595, respectively, and which receive the

previously mentioned projections such as 223 and 224 provided on the upper surface of ribbon 10. A plurality of three compressible springs such as 596 are provided between an upper overhanging part of the support such as 582 and the top of pivoting member such as 586, such springs normally urging or biasing the respective pivoting member 586 downwardly but permitting a limited amount of pivoting of such member about its respective pivot pin such as 588. Such arrangement allows for the pivoting member such as 586 to adjust to different thicknesses of the ribbon such as 10 as well as for different height of projections such as 223 and 224 on ribbon 10. The positioning means such as just described will be further discussed hereinafter.

The ribbon-length break-off or fracturing means is generally designated 601 and includes parts, members or devices such as 602, 604, 605, 606, 607, 598, 610 and 617, which are similar to and correspond with the parts, members or devices such as 582, 584, 585, 586, 587, 588, 590 and 596, respectively, of the above discussed orienting or positioning means. However, the fracturing means such as 601 includes a ribbon-length fracturing device, per se, which is designated 611 and which is affixed to the front portion of pivoting member 606 by the bolts such as 610. Device 611 includes a lower beveled, knife or blade shaped portion which is intended to protrude into the previously mentioned channels or grooves such as 470 extending across the width of the glass ribbon such as 10.

A sliding cam follower 608 is secured, as by suitable bolts or screws such as 609, to the side of pivoting member 606, the cam follower such as 608 having a curved bottom surface as best illustrated in FIG. 22a. A fixed cam designated 612 FIGS. 22d, 22e and 22f, taken in conjunction with FIG. 22 and 22c, is secured, in any convenient manner, to the lower end of a depending support bracket 613 which also supports, above cam 612, a rail member 614 (FIG. 22 and 22c) having a lower surface against which each roller or wheel such as 576 (FIG. 22c) is intended to roll as it passes rail member 614. Rail member 614 provides a positive hold-down for the blowheads such as 560 which carry the ribbon-length break-off or fracturing devices such as 601 shown in FIGS. 22a and 22c. The above mentioned fixed cam 612 has a shortened portion 615 (FIG. 22d) which has an upper surface 616 (FIG. 22e) which slopes upwardly, as best illustrated in FIG. 22f, and upwardly along which the aforementioned curved bottom surface of cam follower 608 (FIGS. 22a and 22c) is intended to slide. This will be discussed further hereinafter in an operational example of the invention. It is, however, now pointed out that since, as previously mentioned, a plurality of thirty two blowheads such as 560 are used in the ribbon length crack-off or fracturing apparatus such as 475, a fracturing means such as 601, per se, is provided on each eighth blowhead such as 560 for a total of four such fracturing means. Also, in total, a plurality of eight positioning means such as 581 are provided and are associated with said fracturing means such as 601, one such positioning means being provided on each blowhead such as 560 which is adjacent a blowhead having a fracturing means such as 601 provided thereon.

Returning to FIG. 1 of the drawings, there is attached to support member 14 a pressurized fluid flow control means designated generally 620 and including an input drive shaft 621 by which rotational power or energy is supplied to the control means 620. Shaft 621 is connected to the previously mentioned power train which drives the shaft but which, as previously mentioned, is not shown in the drawings for purposes of simplification thereof. One end of a flexible pressurized fluid conduit 622 is connected to flow control means 620 and the other end of such conduit is connected to a suitable source of pressurized fluid whose flow through flow control means 620 is controlled by suitable valves housed in means 620 and actuated in a selected sequence by the rotation of drive shaft 621. A second fluid conduit 623 has a first end connected to flow control means 620 while the second end of such conduit leads to a suitable fluid sink such as 624 shown only schematically in FIG. 1 in the usual manner. The aforesaid source of pressurized fluid is also omitted from the drawings for purposes of simplification.

A plurality of flexible pressurized fluid conduits 272, 273, 282, 283, 362, 363, 372 and 373 are also shown connected to control means 620. Conduits 272 and 273 are the same conduits as those shown in FIGS. 4, 10 and 11 as connecting to the opposite ends of pressurized fluid cylinder 266. Conduits 282 and 283 are the same conduits as those shown in FIGS. 10 and 12 as connecting to the opposite ends of pressurized fluid cylinder 276. Similarly, conduits 362 and 363, and conduits 372 and 373 are the same conduits as those shown in FIG. 4 as connecting to opposite ends of pressurized fluid cylinders 365 and 366, respectively. Pressurized fluid flow control devices or means such as 620 are well known to those skilled in the art. However, such means will be discussed further hereinafter.

Briefly further referring to FIG. 1 taken in conjunction with FIG. 22, there is indicated diagrammatically at the left hand end of the apparatus of the present invention, and in broken line form, apparatus of the prior art and designated by reference characters 625, 626 and 627. Such reference characters designate parts which may correspond, for example, to the plate sections such as 153, 154 and orifice rail such as 178, respectively, shown in FIGS. 2 and 9 of the previously cited U.S. Pat. 1,790,397 to W. J. Woods et al. In such case, the cullet conveyor such as 353 of Woods et al. is replaced by the conveyor such as 410 of the present invention and, referring to FIGS. 44 and 45 of the Woods et al. patent, the stripper disc such as 352 and the crack-off bar such as 354 shown in such drawing figures of such patent are dispensed with. Thus, the ribbon such as 79' of the cited patent may be permitted to be conveyed to conveyor 410 as illustrated in FIGS. 1 and 22 of the present invention. Since the apparatus of the present invention is intended to break off or crack off from a parent ribbon ribbon lengths each supporting the same number of pendent articles or bodies, and then handling such ribbon lengths as previously discussed in general terms, reference is also made to FIG. 1a of Letters Patent of the United States, issued Jan. 9, 1934 to W. L. Van Ness for Glass Working Apparatus. There is shown in the upper left hand part of said FIG. 1a, a length of ribbon supporting two pendent bodies or articles such as jars. The apparatus of the

present invention can be readily adapted to handling the ribbon shown in said FIG. 1a of the patent to Van Ness and the bodies or articles depending from such ribbon, as will be readily apparent to those skilled in the art.

As previously mentioned, FIG. 26 comprises a table detailing the shape of a cam groove embodied in a cam employed in practicing the invention, such cam being the main cam 25 which makes two full revolutions (720°) for a complete cycle of operations, and said cam groove being groove 27 including circumferential portions or sections 27a and 27b, and helical or spiral portion or section 27c illustrated in FIGS. 1 and 2 of the drawings. Referring to FIG. 26, it is pointed out that circumferential groove section or portion 27a of groove 27 extends from a 0° point on the periphery of cam 25 and circumferentially about such periphery to a 325° point thereon. The location of such points will be hereinafter further discussed in more detail in an operational example of the invention. The helical or spiral section or portion 27c of groove 27 includes an acceleration groove section which extends about the periphery of cam 25 from said 325° point to a 340° point for a total of 15°, a constant velocity groove section which extends about the periphery of cam 25 from said 340° point to a 590° point (from the 340° point to the aforesaid 0° or 360° point and to a 230° point in a second revolution about cam 25) for a total of 250°, and a deceleration groove section which extends about the periphery of cam 25 from said 590° point to a 625° point for a total of 35°. Circumferential groove section or portion 27b of groove 27 extends circumferentially about the periphery of cam 25 from said 625° point to a 940° point (from the 625° point to the 0° or 720° point and to a 220° point in a third revolution about cam 25) for a total of 315°. Thus, there is no cam groove for a total of 140° in the third revolution about cam 25, that is, from said 940° point to the 0° or 1080° point at the end of said third revolution. The location of the above-mentioned 625° and 940° points will also be hereinafter further discussed in more detail in an example of the operation of the apparatus of the invention.

The table shown in FIG. 26 also sets forth, in linear inches, the distances from a zero line that the centerlines of various portions or sections of cam groove 27 are located, said zero line being the centerline of circumferential section or portion 27a of groove 27 and said distances being from the latter centerline in straight lines along the length of cam 25. As will be readily apparent, the distances in linear inches given in the table of FIG. 26 are correlated with selected points in degrees about the outer periphery of cam 25. Thus, the table of FIG. 26 gives an example of the path of groove 27 about cam 25 and will enable one skilled in the art to readily duplicate a path such as 27 about a cam such as 25.

A previously mentioned, there is shown in FIG. 31 a time chart setting forth examples of speeds of parts of the apparatus of the invention relative to one another when handling successive ribbon lengths each having a length of 36 inches and each supporting on 4.5 inch centers a plurality or bank of eight pendent articles or bodies which are termed in the chart as containers. The time chart is believed to be substantially self-explanatory but a brief discussion concerning the chart may be expedient.

The ribbon machine speed set forth in the chart refers to the forming speed of a machine such as disclosed in the cited patent to W. J. Woods et al. or the cited patent to W. L. Van Ness. The main cam revolutions of the chart refer to the revolutions of cam 25 of the apparatus of the present invention. The carriage forward times refer to the time periods required for each slide member such as 97 and 100 to move from its left hand position to its right hand position (viewing FIG. 4 for example) on main carriage or sliding support member 65, while the carriage return times refer to the time periods required for each said slide member to subsequently move in the opposite direction to said left hand position on main carriage member 65.

The container bank pickup and discharge times given in the time chart are the times required for each pickup head or device, such as 170 and 290 shown in FIGS. 2, 3 and 4 of the drawings, to pickup and discharge, respectively, a bank of containers, that is, a ribbon length such as 225 supporting a bank or plurality of pendent articles or bodies such as 226. The carriage return chain speed refers to the linear speed in inches per second of the chains such as 51 and 61 shown, for example, in FIG. 1. The carriage index times given in the time chart are the time periods required for the main carriage or sliding support member 65 to move between the rear and the front of the apparatus (from left to right viewing FIG. 3) or from the front to the rear of the apparatus, that is, from right to left when viewing FIG. 3. The cycle time of two carriages or a complete cycle given in the time chart of FIG. 31 is a full cycle of both slide members 97 and 100 simultaneously (or of either one of such members alone) since they both move completely through their respective paths of movement during the time period of each complete cycle of operations.

OPERATIONAL EXAMPLE OF THE INVENTION

For the purpose of an operational example of the invention, it will be assumed that there is provided a rotational power train which has its input end or input shaft connected to an output shaft of the prime mover which drives or supplies power to the previously mentioned ribbon forming machine or apparatus. Such a power train would include suitable gear boxes, drive shafts, couplings and pillow blocks such as are well known in the art, and the input shafts, such as 621 of fluid flow controller 620 (FIG. 1) 32 of gear box 31 (FIGS. 1 and 3) 78 of gear box 77 (FIGS. 1 and 3) 406 of gear box 404 (FIGS. 3 and 24) 456 of gear box 454 (FIGS. 1 and 21) and 521 of gear box 520 (FIGS. 22, 23 and 23a) would be suitably connected into said power train in a driven relationship therewith. It will also be assumed that the otherwise free end of the conduit 622 of fluid flow controller 620 is connected to the previously mentioned source of pressurized fluid. It will be further assumed that the previously mentioned prime mover is energized and that the ribbon forming apparatus or machine previously discussed is forming the ribbon such as 10 and is supplying such ribbon with its pendent articles or bodies such as 226 to the apparatus of the present invention which, preferably, is also being driven from said prime mover.

Under the above assumed conditions, conveyor 410 (FIGS. 1, 15, 16, 21, 22 and 23) is operating to receive the ribbon 10 from the ribbon machine or forming ap-

paratus (FIGS. 1 and 22) onto the ribbon support arms such as 465 as previously discussed, that is, with the pendent articles or bodies such as 226 depending from the ribbon 10 between the ribbon support arms such as 465. The linear speed of movement of the support arms such as 465 must be equal to the linear speed of movement of the aforementioned plate sections (625 and 626) of the ribbon forming machine, that is to say, equal to the linear speed of movement of ribbon 10, as is believed obvious. The ribbon 10 is carried by said support arms of conveyor 410 beneath the previously discussed ribbon-length crack-off, break-off or fracturing apparatus 475 as best illustrated in FIG. 22, and such apparatus is also being moved through its looped path of travel 580 at a linear speed equal to the linear speed of ribbon 10. As each blowhead such as 560 of the ribbon-length fracturing apparatus 475 moves through the lower left hand quadrant (viewing FIG. 22) of the looped path of travel 580 of such blowheads, the rollers such as 576 and 577 of each respective blowhead such as 560 move into the tracks or channels 552 and 553 of members 550 and 551, respectively (FIGS. 1 and 23a) and each respective blowhead is thereby actuated downwardly so that its sliding contact member 567 moves beneath and contacts the bottom surface of blowbox 568 and slides therealong during the continued movement of the respective blowhead through said looped path of travel. Said downward actuation of the blowheads such as 560 also causes the blowtips such as 569 of successive blowheads to be inserted into the openings at the top of successive ones of said pendent articles or bodies such as 226 depending from the moving ribbon 10, and the hold-down plates such as 570 of each successive blowhead successively contact the top surface of ribbon 10.

The movement of the blowheads such as 560 through their looped path of travel 580 is also synchronized, with the movement of ribbon 10 by the support arms such as 465 of conveyor 410, so that the aforesaid lower portion of the ribbon-length fracturing means such as 611, per se, and carried by each eighth blowhead such as 560 successively enter into each successive groove or channel such as 470 provided in ribbon 10 between each group of eight pendent articles or bodies such as 226. At substantially the same time the ribbon contacting devices such as 591, adjacent each respective fracturing means such as 611, are actuated downwardly so that each respective pair of projections such as 223 and 224 provided on the upper surface of ribbon 10 enter into the recesses or cavities such as 594 and 595 of the respective devices such as 591. The initial downward actuations of the ribbon-length means such as 611 and of the ribbon contacting devices such as 591 are, of course, caused by the aforesaid downward actuations of the blowheads such as 560 by the tracks or channels 552 and 553 of members 550 and 551, respectively. Blowbox 568 maintains the blowheads such as 560 and their associated devices and means in their downward positions during continued sliding movement of each respective sliding member such as 567 of the blowheads 560 along the bottom surface of the blowbox.

Referring to FIGS. 22 and 22a, taken in conjunction with FIGS. 22d, 22e, and 22f, as each blowhead such as 560 carrying a ribbon-length fracturing means such as

601 reaches the location of fixed cam 612 (FIG. 22 and 22c) the curved bottom surface of sliding cam follower 608 of the respective fracturing means slides upwardly along surface 616 of shortened portion 615 of cam 612 causing pivoting member 606 of the respective fracturing means 601 to pivot about its pivot pin 598 thereby causing compression of the associated springs such as 617 and raising the respective ribbon-length fracturing device 611 so that its lower blade-shaped portion is temporarily somewhat withdrawn from the groove or channel 470 in ribbon 10 into which it previously protruded.

Subsequently, when the trailing edge of the aforesaid cam follower 608 completes its sliding movement over surface 616 of shortened portion 615 of cam 612, the aforesaid springs such as 617 abruptly reactuate the associated ribbon-length fracturing device 611 downwardly to cause the edge of the lower portion of such device 611 to impart, within the groove or channel such as 470, a sharp blow to ribbon 10 thereby causing fracturing of such ribbon along said groove or channel to provide a ribbon length, such as 225, of ribbon 10. During the fracturing operation of the apparatus as just described, the roller or wheel such as 576 of the respective blowhead such as 560 rolls against the lower surface of the previously discussed rail member 614 to provide a positive hold-down for such blowhead. As is readily apparent, a similar operation takes place each time one of the ribbon-length fracturing devices passes the actuating means therefor, that is, passes the fixed cam 612, and a succession of substantially equal length ribbon lengths such as 225 each supporting a plurality or succession of eight equally spaced-apart pendent articles or bodies, such as jars or containers for example, are thereby continuously provided and are conveyed by the support arms, such as 465 of conveyor 410, further in a forward direction to the entrance end of the ribbon-length handling apparatus whose operation will now be described and which is located at a handling station which is, in turn, located in the path of travel of conveyor 410, that is, in the path of movement of the support arms such as 465 of conveyor 410.

As previously mentioned, the main drum or cylindrical cam 25 of the apparatus makes two complete revolutions for a total of 720° for each full cycle of operation of one or both of the slide members such as 97 and 100 since such slide members and their associated ribbon-length pickup devices or heads 170 and 290, respectively, move simultaneously through their respective paths of movement during the time period of each complete cycle of operations. However, the beginning and end locations in said paths of movement for each said slide member and its respectively associated device differ, and said member and associated devices also move in generally opposite directions during said simultaneous movements through their respective paths of movement. Referring to the previously discussed time chart of FIG. 31 it will be noted that the speed of revolution of main cam 25 is related to the speed of movement of the ribbon 10 (the ribbon lengths such as 225) which is directly related to the speed of the ribbon machine which forms the ribbon having pendent articles or bodies depending therefrom. (Each ribbon length is termed in the time chart as a

container bank). However, the operation of the apparatus to now be discussed has a direct relationship with the revolutions of cam 25 and, therefore, it is believed expedient to give the operational example of the apparatus in relation to the previously mentioned 720° through which cam 25 rotates or revolves in said two revolutions thereof for one complete cycle of operation of the previously mentioned apparatus. This will become more apparent with reference to FIGS. 27, 28, 29 and 30 of the drawings which will now be discussed.

FIG. 27 schematically illustrates the horizontal path of movements of slide members 97 and 100 (A and B, respectively, in FIG. 27) and their associated parts. FIG. 28 schematically illustrates vertical movement of ribbon-length pickup device or head 290 and its associated parts, and it will be noted from FIG. 28 that 300° of revolution of cam 25 (410° to 710° of the second revolution of cam 25) are required for a forward movement of such apparatus and, for the return movement of such pickup head 290 and its associated parts, 300° of revolution of cam 25 (50° to 350° of the first revolution of cam 25) are also required. At the end of said forward movement, pickup head 290 and its associated parts dwell in their raised position for 60° of revolution of cam 25 and at the end of said return movement such apparatus also dwells in its raised position for 60° of revolution of cam 25. Similarly, FIG. 29 schematically illustrates vertical movement of ribbon-length pickup device or head 170 and its associated parts, and the degrees of revolution required for a forward movement of such apparatus is also 300° of revolution of cam 25 (50° to 350° of the first revolution of cam 25) and, for the return movement of such pickup head 170 and its associated parts, 300° of revolution of cam 25 (410° to 710° of the second revolution of cam 25) are also required. At the end of each of said forward and return movements, pickup head 270 and its associated parts dwell in their raised positions for 60° of revolution, of cam 25. FIG. 30 schematically illustrates vertical movement of the gang or plurality of the ribbon length supporting devices such as 386 shown in FIGS. 24 and 25 of the drawings. In each of the FIGS. 28, 29 and 30 lines sloping to the left are intended to indicate upward movement while lines sloping in the opposite direction or to the right are intended to indicate downward movement. Since said horizontal and vertical movements of the components and parts often occur simultaneously it will be expedient to place FIGS. 27, 28 and 29, side by side, with FIG. 27 located in the center and FIGS. 28 and 29 on the left and right hand sides, respectively, of FIG. 27. As previously indicated, slides A and B in FIG. 27 correspond to slide members 97 and 100 (FIG. 4) respectively, while cam followers C and D in FIG. 27 correspond to cam followers, or the rollers or wheels 103 and 104, respectively, shown in FIG. 4. Cam followers E and F, (FIG. 27) correspond, respectively, to cam follower, or roller or wheel, 120 (shown in FIGS. 5 and 6) and its counterpart (not shown) which follow cam tracks or channels 82 and 87, respectively, in cam members 81 and 86, respectively (FIG. 4).

The lower circle in FIG. 27 represents the left hand end (viewing FIGS. 1 and 2) or the ribbon-length entrance end of the handling apparatus as indicated by the arrow in FIG. 27 designating the centerline of the

ribbon. The smaller broken line circle within the lower circle in FIG. 27 represents portion or section 27a of cam groove 27 embodied in cam 25. Similarly, the upper circle in FIG. 27 represents the right hand end (viewing FIGS. 1 and 2) of the handling apparatus and the smaller broken line circle within the upper circle represents portion or section 27b of cam groove 27 embodied in cam 25. The space between the lower and upper circles in FIG. 27 represents the linear distance between the centerlines of cam groove sections 27a and 27b taken along the length of cam 25, that is to say, the linear extent of the helical or spiral portion or section 27c of cam groove 27 taken in a straight line along the length of cam 25. The purpose of the degree points indicated on the lower and upper circles in FIG. 27 will become apparent from the discussion which follows.

It will be assumed, for purposes of the operational example, that the speed of the ribbon lengths being supplied to the handling apparatus is 6 inches per second as set forth in the first column of the time chart of FIG. 31. Under such assumption cam 25 revolves at 60° per second counterclockwise or in the direction indicated by the arrows in FIG. 27 and it will be further assumed that the revolutions of such cam are in proper synchronism with the movement of each of the ribbon lengths into the entrance end of the handling apparatus, that is to say, that the revolutions of cam 25 are synchronized with the movement of the ribbon lengths so that a ribbon-length pickup head or device may properly contact each ribbon length for handling thereof as discussed below. The starting points for slides A and B in the example of the cycle of operations of the apparatus to be given are those indicated schematically by the solid rectangles in FIG. 27. The broken line rectangles schematically indicate dwell positions of slides A and B during said example of the cycle of operations of the apparatus. Said starting points of slides A and B correspond to the positions of slide members 97 and 100, respectively, and main slide member 65 shown in FIGS. 1 through 4, that is, when viewing FIG. 4 for example, with main slide member 65 at the extreme end of its path of travel to the front of the apparatus, and with slide members 97 and 100 at the extreme left and right hand ends, respectively, of their paths of travel on main slide member 65.

It will now be assumed that slides A and B have been dwelling in their aforesaid starting positions for 10° of revolution of cam 25 and, at some point during the second 5° of said 10° of revolution, the ribbon-length pickup device 290 carried by slide B has released the ribbon length then supported by such pickup device onto the top surfaces of the horizontally extending upper portions such as 388 of the ribbon-length supporting devices such as 386 (FIGS. 24 and 25). Slides A and B dwell in their respective starting positions for an additional 5° of revolution of cam 25. The beginning of such additional 5° of revolution is considered the starting point of a complete cycle of operation and, at such point, the 0° point on cam 25 (starting point of section 27a of cam groove 27) is in the position (lower left quadrant) indicated in the lower circle of FIG. 27. At the end of said additional 5° of additional revolution of cam 25, actuating arm 73 (FIGS. 3 and 4) which connects main slide member 65 to crank arm 75 of oscillatory gear box 77 is actuated to move said slide

member 65 to the end of its path of movement at the rear of the apparatus shown in FIGS. 3 and 4 (in the left hand direction viewing FIGS. 3 and 27). Such movement of member 65 is effected during the next 30° of revolution of cam 25. Such movement is indicated in FIG. 27 as a 30° index and, during the movement, cam followers C and D of slides A and B, respectively, move into and out of sections 27a and 27b, respectively, of groove 27 in cam 25. Cam follower C starts to be engaged in said groove section 27a after approximately 15° of said next 30° of revolution of cam 25, and is completely engaged in such groove section 27a at the end of such 30° of revolution, that is, is completely engaged in said groove section 27a at the 310° point of such groove section which is then at the bottom center of the lower circle of FIG. 27. Slides A and B now dwell in their respective positions for the next 15° of revolution of cam 25, that is, until the 325° point of groove section 27a and indicated on the lower circle in FIG. 27 reaches the bottom center point of such lower circle.

Following the above dwell period of slides A and B, slide B is engaged by one of the rollers or wheels such as 153 being carried by chain 61 (FIG. 1) and slide B is moved by such roller or wheel through a path of movement towards the entrance end of the apparatus (left hand end viewing FIG. 4). Said movement occurs during the next 300° of revolution of cam 25 or from the 50° point in the first revolution of such cam to the 350° point in such revolution of the cam. Such movement, however, includes an acceleration portion during approximately 77.2° of revolution of cam 25, a constant velocity portion during approximately the next 145.6° of revolution of cam 25 and a deceleration portion during approximately the next 77.2° of revolution of cam 25 for said 300° of revolution. Also, during said movement of slide B, roller F, associated with such slide and with pickup head or device 290, follows cam track 87 in cam member 86 (FIG. 4) and, thus, roller F and pickup device 290 are moved in a path corresponding to the configuration of said track 87. Such path slopes to the left (viewing FIG. 27) for approximately the first 176.46° of said 300° of revolution of cam 25 and then continues in a straight line for approximately the next 123.54° of such 300° of revolution of cam 25. Such paths of movement of slide B, and of roller F and the associated pickup device 290, are represented in FIG. 27 by the broken lines designated generally as G and H, respectively.

Simultaneously with the above described movements of slide B and its associated devices, that is, when the 325° point of groove 27 on cam 25 reaches the bottom centerpoint in the lower circle of FIG. 27, cam follower C of slide A moves out of section 27a of cam groove 27 and into the helical or spiral section 27c of such cam groove of cam 25. Helical groove section 27c includes, as previously pointed out, an acceleration section of 15° of revolution of cam 25, and cam follower C and, thereby, slide member A, are accelerated by said acceleration section of groove section 27c to the speed of a ribbon length which is then moving below ribbon-length pickup device or head 170. Simultaneously with a latter part of the acceleration period of slide member A and during a part of a constant velocity period following such acceleration period, the top surface of cam follower 188 (FIG. 5) slides along and is depressed

downwardly by the bottom surface of cam 83 (FIG. 7) during such sliding movement. Such downward actuation of cam follower 188 causes corresponding downward actuation of ribbon-length pickup device or head 170 to its position illustrated in FIG. 5. As schematically illustrated in FIG. 29, said downward actuation continues for approximately 38.21° of revolution of cam 25 and, at the end of such downward actuation, pressurized fluid is supplied from fluid flow controller 620 (FIG. 1) to conduits 273 and 283 (FIGS. 10, 11 and 12) while conduits 272 and 282 are connected through said controller 620 to fluid sink 624 (FIG. 1). This operation causes actuation of the piston rods 269 and 279 of pressurized fluid cylinders 266 and 276, respectively, of pickup device 170 and the ribbon-length pickup fingers such as 253 of such pickup device are actuated to move under the ribbon length such as 225 and contact the sides of such ribbon length for subsequent pickup thereof. (See FIG. 5). Pickup device 170 dwells in its downward position for approximately 47.5° of revolution of cam 25 (FIG. 29) and, following such 47.5° of revolution, pickup device 170 is actuated upwardly for approximately the next 184.79° of revolution of cam 25. (See FIG. 29). Such actuation causes pickup device 170 to take and raise the contacted ribbon length such as 225 and separate the trailing edge thereof from the leading edge of the next succeeding ribbon length being conveyed by conveyor 410, such edges heretofore being generally in contact with each other at the fracturing or crack-off groove such as 470 between the two ribbon lengths. During said 184.79° of revolution of cam 25, pickup device 170 continues to raise and, thereby, assure clearance between said trailing edge of the taken ribbon length and said leading edge of the next succeeding ribbon length.

While pickup device 170 dwells in its downward position for said 47.5° of revolution of cam 25 (FIG. 29) slide A continues to be moved through the constant velocity section or portion of helical groove section 27c of cam groove 27 of cam 25, such constant velocity section continuing for 250° of the first revolution of cam 25 (FIG. 27). However, at the end of approximately 108.54° of said additional 250° of revolution of cam 25, roller or cam follower E or slide A is started to be actuated to the right (viewing FIG. 27) by cam groove or channel 82 in cam member 81 (FIG. 4) a ribbon-length pickup device 170 and its taken ribbon length are moved to the right correspondingly, that is, towards the front of the apparatus (viewing FIG. 4). At the end of said 250° of revolution of cam 25, cam follower C of slide A moves into the deceleration section of helical section 27c of cam groove 27 in cam 25 and for the next 35° of revolution of cam 25 (FIG. 27) the forward movement of slide A is decelerated to zero velocity and, at the end of such 35° of revolution (350° of the first revolution of cam 25) the movement to the right of roller E and pickup device 170 is also terminated. Pickup device 170 and its taken ribbon length are now located over the location of the horizontally extending upper portions such as 388 of the ribbon-length support arms such as 386 (FIGS. 24 and 25) when such arms are in their raised positions as hereinafter further discussed.

At the end of said 35° of revolution of cam 25, that is, at the end of the deceleration section of the helical sec-

tion 27c of cam groove 27, cam follower C of slide A moves into cam groove section 27b at the 350° point in the first revolution of cam 25, that is, at the 625° point of cam groove 27b in cam 25, such point now being at the bottom center point in the upper circle in FIG. 27. Slide A now dwells for the next 15° of revolution of cam 25, that is, until the 640° point of cam groove 27 of cam 25 reaches the bottom center point of said upper circle. During such dwell period or, more specifically, between the 350° and 355° points (FIG. 30) in the first revolution of cam 25, the ribbon-length support arms such as 386 are raised under the ribbon length supported by pickup device 170, and the top surfaces of said upper portions such as 388 of the support arms contact the lower surface of the ribbon length such as 225 for receipt of such ribbon length. Said ribbon support arms such as 386 now dwell for 5° revolution of cam 25 in their raised positions, that is, between the 355° and 360° points (FIG. 30) in the first revolution of cam 25 and, during such dwell period, pressurized fluid flow controller 620 (FIG. 1) is actuated to terminate the supply of pressurized fluid to conduits 273 and 283 and connect such conduits to conduit 623 and, thereby, to fluid sink 624, while conduits 272 and 282 are disconnected from conduit 623 and are connected through said controller to the source of pressurized fluid previously mentioned. This operation causes reactivation of piston rods 269 and 279 of fluid cylinders 266 and 276, respectively, and the ribbon-length pickup fingers such as 253 of pickup device 170 are reactivated to release the supported ribbon length such as 225 onto the top surfaces of said upper portions such as 388 of the support arms such as 386. At the 360° point (FIG. 30) in the first revolution of cam 25, the ribbon-length support arms start to lower and, prior to or at the 365° point in the second revolution of cam 25, the ribbon length such as 225 is clear of pickup device 170.

At the above-mentioned 365° point in the second revolution of cam 25, oscillatory gear box 77 is actuated to move main slide member 65 towards the end of its path of movement at the front of the apparatus shown in FIGS. 3 and 4 (in the right hand direction viewing FIGS. 3 and 27). Such movement of member 65 is performed during the next 30° of revolution of cam 25 and such movement is indicated in FIG. 27 as a 30° index. During such index movement cam followers C and D, respectively, of slides A and B, respectively, move out of and into cam groove sections 27b and 27a, respectively, of cam groove 27. At approximately the 380° point in the second revolution of cam 25, cam follower C is completely disengaged from groove section 27b, and at the same point cam follower D begins to engage with groove section 27a of cam groove 27 and is completely so engaged at the 395° point in the second revolution of cam 25.

Slide A dwells for the next 15° of revolution of cam 25 (to the 410° point in the second revolution of cam 25) at the position indicated by the dotted line outline of such slide in the upper right hand portion of FIG. 27. Slide B simultaneously dwells, for said 150° of revolution of cam 25, at the position indicated by the dotted line outline of such slide at the bottom center of the lower circle in FIG. 27. Since the actuation of slide B from said bottom center position in the lower circle of

FIG. 27 to its original starting position, indicated at said bottom center of the upper circle of such drawing figure, is similar to that discussed for slide A between said positions, no detailed discussion of such actuation of slide B is considered necessary.

Returning now to slide A which is dwelling in its position mentioned above, and taking FIGS. 27 and 29 in conjunction with FIGS. 1, 2, 2b and 2c, the return movement of slide A to its original position will now be discussed.

During the above-mentioned dwell period of slide A for said 15° of revolution of cam 25, one of the wheels or rollers such as 133 carried by chain 51 moves downwardly into the channel between vertical member 141 (FIG. 2c) and pivoting member 144 associated with slide member 97 (slide A in FIG. 27). Now, during the movement of said one wheel or roller such as 133 through the lower right hand quadrant of its path of movement by chain 51 illustrated in FIG. 2c, said roller presses against the right hand face of member 141 and slide member 97 is thereby urged and moved, as indicated by the dotted line I in FIG. 27, in the direction towards the original starting position of slide A.

During approximately the next 77.20° of revolution of cam 25, slide A is accelerated by said one roller such as 133 from zero velocity to a period of constant velocity which is indicated in FIG. 27 as lasting for the next 145.6° of revolution of cam 25. Following said period of constant velocity said one roller 133 begins to move through the lower left hand quadrant of its path of movement by chain 51 illustrated in FIG. 2a and up along the right hand face of member 141 and, during approximately the next 77.2° of revolution of cam 25, slide A is thereby decelerated from its aforesaid constant velocity to zero velocity at which point (the 710° point in the second revolution of cam 25) slide A (slide member 97) has reached its extreme left hand position on main slide member 65 (viewing FIGS. 1, 2 and 4). Said one roller such as 133 then moves out of the upper end of the aforesaid channel between vertical member 141 and pivoting member 144.

It is pointed out that pivoting member 144 provides a backup for said one roller 133 when such roller is moving slide A (slide member 97) to its original starting position as mentioned above. In other words, the pushing of said one roller such as 133 against the right hand face of member 141 as mentioned above tends to tip or tilt such roller on chain 51 but the left hand face of pivotal member 144 contacts the periphery of roller 133 and prevents such tipping or tilting. It is also pointed out that after slide member 97 (slide A in FIG. 27) reaches the left hand end of its path of travel on main slide member 65 and said one roller such as 133 moves out of the upper end of the channel between members 141 and 144 (FIG. 2b) one or more of the rollers such as 133 on chain 51 and following behind the previously mentioned one roller such as 133 may be moved through the aforementioned lower left hand quadrant (FIG. 2a) of the path of travel of chain 51 while slide A (slide member 97) is still dwelling in its original starting position previously discussed. Under such conditions, each said additional roller such as 133 contacts the right hand face of pivoting member 144, and the biasing provided by spring 148 is thereby overcome and member 144 pivots about screw 145 to per-

mit the passage of each said additional roller such as 133 between said right hand face of member 144 and the left hand face of arcuate member 136. At such time the left hand face of arcuate member 136 provides a backup for said one or more additional rollers to prevent tipping or tilting thereof on chain 51.

With further reference to FIGS. 4, 5 and 27 of the drawings, during the above-discussed return of slide member 97 (slide A in FIG. 27) to its original starting position, roller, wheel or cam follower 120 (FIG. 5) follows cam groove or channel 82 in cam member 81 (FIGS. 4 and 5) and the pickup head or device 170 and its associated apparatus moves through a path of travel represented by the dotted line J in FIG. 27, such path corresponding in configuration to that of pickup device 170 when being moved in the forward direction by cam 25 but, of course, the movement through such path J being in the reverse or return direction of the pickup head and its apparatus. At the end of the 10° of revolution of main cam 25 mentioned at the start of the description of the operational example of the apparatus, such cam will have completed its second revolution for the aforesaid 720° in the two revolutions of such cam required for one complete cycle of the apparatus and another cycle of such apparatus will then begin.

Since, as previously mentioned, the operation of slide B and its associated ribbon-length pickup device (slide member 100 and pickup device 290) is similar to that just described in detail for slide A and its associated pickup device (slide member 97 and pickup head 170) no detailed description of the operation of the former apparatus is given since such operation will be readily apparent to those skilled in the art from said detailed description of the operation of slide A taken in conjunction with FIGS. 27 and 28 of the drawings.

Briefly referring further to FIG. 30, it is pointed out that the line designated A and B is for the purpose of indicating selected positions of slides A and B relative to selected vertical positions of the ribbon-length support arms such as 386 of FIGS. 24 and 25. The left hand line of FIG. 30 represents only dwell periods and generally vertical movement periods of said support arms. It will be noted that the support arms such as 386 are moving downwardly at the aforesaid 5° point in the first revolution of cam 25 and, therefore, such arms are in the clear of ribbon-length pickup device 270 when the indexing of main slide member 65 occurs during the 30° (5° to 35°) of the first revolution of cam 25 previously discussed. The support arms such as 386 between the 5° and 140° points in the first revolution of cam 25 continue their downward movement to their fully lowered position indicated by the dotted lines in FIG. 24. Just prior to the support arms reaching their said fully lowered position the bottom surface of the respective ribbon length such as 225, then carried by the support arms, contacts the upper surfaces of the conveyor belts such as 376 and 377 (FIGS. 24 and 25) and said ribbon length is, thereby, delivered to such belts for transfer or conveyance thereby away from the location of the handling apparatus and to another station or location for additional operations to be performed on the respective ribbon length and/or its pendent bodies or articles such as 226. It will be understood that said conveyor belts are being continuously driven through their

5 looped path of travel during the operation of the ribbon-length handling apparatus. The support arms such as 386 dwell in their lowered positions for the next 160° (140° to 300°) in the first revolution of cam 25 (FIG. 30). At the end of said dwell period the support arms are again actuated in their upward directions to receive the ribbon length then being held by pickup device 170 as previously described in the example of the operation of such pickup device. After receiving said ribbon length and after a dwell period of the support arms in their fully raised positions for 5° (355° to 360°) in the first revolution of cam 25, said support arms, as also previously described, begin to lower to transfer the received ribbon length to the conveyors such as 376 and 377. By this description and from a brief study of FIG. 30, it will be readily apparent that the ribbon-length support arms such as 386 are actuated through two full cycles of their operation during each said 720° of revolution of cam 25 and that, during alternate ones of such two full cycles, of operation of the support arms such as 386, the support arms alternately receive ribbon lengths such as 225 from the pickup devices 170 and 290.

25 Many modifications of the apparatus of the invention are possible. For example, the dwell periods of the slide members such as 97 and 100 and their associated ribbon-length pickup devices 170 and 210 can be varied, within limits, from those set forth. Further, if found necessary or expedient to do so because of a substantial increase in the forming speed of the aforesaid ribbon machine and the corresponding increased linear speed of movement of the ribbon such as 10, as previously mentioned, one or more additional sets of handling apparatus such as represented by the broken line block diagram designated 650 in FIG. 21 of the drawings can be provided for handling of the ribbon lengths. Such additional sets of handling apparatus would be identical to the one shown and described except that another ribbon-length crack-off apparatus or another conveyor such as 410 would not necessarily be required. If, for example, only one additional set of handling apparatus, such as apparatus 650 in FIG. 21, is provided, the two sets of apparatus could handle alternate ones of the ribbon lengths, the ones of such ribbon lengths not handled by the first set of apparatus being carried by conveyor 410 to the set of apparatus designated 650. In other words, the first set of handling apparatus would, for example, handle odd-numbered ones of the successive ribbon lengths while the additional set of handling apparatus would then handle the even numbered ones of such lengths. Furthermore, if two sets of handling apparatus are provided as mentioned above and the speed of movement of the ribbon such as 10 is sufficiently slow, one of the pickup devices and the associated parts of each such set of handling apparatus can be removed for repairs etc. while the two remaining pickup devices etc. of such sets alternately handle alternate ones of the successive ribbon lengths.

60 In the light of the above discussion it will be readily recognized by those skilled in the art that various modifications and changes can be made in the apparatus arrangement of the invention and, although only a single embodiment of the invention is shown and described in detail, it should be understood that many changes and modifications may be made in the inven-

tion within the purview of the appended claims without departing from the spirit and scope thereof.

We claim:

1. A method of handling a succession of equal lengths of a ribbon of a substantially rigid material, such lengths moving on a conveyor in a selected direction through a selected path of travel with the trailing end of each preceding said length disposed adjacent to or abutting the leading end of the respective next succeeding said length, such method comprising the sequential steps of:
  - A. following above one of said ribbon lengths with a pickup device while initially moving such device in said selected direction at the same speed as the speed of such one ribbon length,
  - B. lowering said pickup device into contact with said one ribbon length and actuating such device to take such length while continuing said initial movement of the pickup device,
  - C. raising said pickup device and said one ribbon length to clear said conveyor while continuing said initial movement of the pickup device whereby clearance is also provided between the trailing end of said one ribbon length and the leading end of the next succeeding ribbon length,
  - D. moving said pickup device in a direction laterally of said selected direction simultaneously with the continued movement of such device in such selected direction,
  - E. terminating the movements of said pickup device in said directions,
  - F. actuating said pickup device to release said one ribbon length onto conveying means for transferring such ribbon length in a direction away from said path of travel and to a desired location, and

G. returning said pickup device to its original position above said selected path of travel of said ribbon lengths in preparation for handling a succeeding ribbon length identically to the described handling of said one of said ribbon lengths.

2. The method in accordance with claim 1 and including the preliminary step of successively fracturing said ribbon at each of equidistant points along the length thereof to sequentially provide said succession of ribbon lengths.

3. The method in accordance with claim 1 and further including, actuating a second pickup device to perform sequential steps similar to steps A through F of the first pickup device during the performance of step

15 G by the first pickup device, and a step similar to step G of the first pickup device during the performance of steps A through F by the first pickup device.

4. The method in accordance with claim 3 and including the preliminary step of successively fracturing said ribbon at each of equidistant points along the length thereof to sequentially provide said succession of ribbon lengths.

5. The method in accordance with claim 3 and including, controlling said pickup devices to perform their respective said sequential steps in a time relationship with the speed of movement of said ribbon lengths through said selected path of travel such that alternate succeeding ones of said ribbon lengths are handled by said first and second pickup devices, respectively.

6. The method in accordance with claim 5 and including the preliminary step of successively fracturing said ribbon at each of equidistant points along the length thereof to sequentially provide said succession of ribbon lengths.
